TELEPHONE SYSTEM

Thomas F. Crocker, Chicago, Ill., assignor to
 Automatic Electric Laboratories, Inc., a cor-
 poration of Delaware

Application January 18, 1943, Serial No. 472,711

27 Claims. (Cl. 179—27)

The present invention relates to telephone systems and more particularly to such systems provided with remotely disposed operator controlled automatic offices or switching centers. Specifically, the present invention relates to improvements in telephone systems of the character disclosed in the copending application of Thomas F. Crocker, Serial No. 418,483, filed November 10, 1941, now Patent No. 2,311,214, granted February 14, 1943.

It is an object of the present invention to provide a telephone system of the type noted comprising improved apparatus for selectively controlling any one of a plurality of links disposed at a remote point over any one of a plurality of control trunks from any one of a plurality of operator positions at a switchboard, whereby connections may be set up and supervised in a ready and efficient manner.

Another object of the invention is to provide in a telephone system including a group of switching links, a group of control trunks extending to an operator switchboard and automatic means for connecting any one of the links in the group having a call signal thereon to an idle one of the control trunks in the group, an arrangement for indicating to the operator switchboard the particular link in the group having a call signal thereon which is connected to the particular control trunk in the group.

Another object of the invention is to provide in a telephone system of the type noted an improved arrangement for registering the identity of the link in the group which is connected to a control trunk in the group and then for transmitting the identification mentioned to the operator position at the switchboard answering the call on the control trunk mentioned incident to the answering operation.

A further object of the invention is to provide a telephone system of the type noted comprising improved switching links, each including a call switch of the numerical type, whereby the call switch of a switching link connected to a control trunk may be selectively controlled directly over the control trunk from an operator position at the switchboard to set up a connection.

A further object of the invention is to provide in a telephone system of the type noted, control trunk equipment terminating the control trunks and associated with the switching links, which equipment embodies improved facilities providing for the answering of calls, the setting up of connections and the monitoring of connections by

way of the switching links over the control trunks.

A still further object of the invention is to provide in a telephone system including a group of switching links and a group of control trunks and a single supervisory conductor extending to an operator switchboard, an improved arrangement whereby call signals on the links in the group are transmitted over idle ones of the control trunks in the group and supervisory signals on the links in the group are transmitted over the single supervisory conductor when it is idle.

Further features of the invention pertain to the particular arrangement of the circuit elements of the system, whereby the above-outlined and additional operating features are attained.

The invention, both as to its organization and method of operation, together with further objects and advantages thereof, will best be understood by reference to the following specification taken in connection with the accompanying drawings, in which Figure 1 illustrates the general arrangement of a telephone system embodying the present invention; Figs. 2 to 10, inclusive, taken together, illustrate the details of a system having incorporated therein the features of the invention as briefly outlined above; and Fig. 11 illustrates the mode of combining Figs. 2 to 10, inclusive, to form a unified system.

30 *Description of the apparatus incorporated in the system*

Referring now more particularly to Fig. 1 of the drawings, the telephone system there illustrated comprises a central office 21, a remote office 31 and a distant office 41. The central office 21 and the remote office 31 are interconnected by a number of control trunks, three being illustrated at 701, 702 and 703, each of the 40 two-wire type, and a single supervisory conductor C705; and the remote office 31 and the distant office 41 are interconnected by a group of toll lines, including the toll line 301, each of the two-wire type. The central office 21 comprises a control switchboard 200 of the automatic type including a number of operator positions, the first, second and third operator positions being respectively indicated at 201, 202 and 203 and an interrupter 26; the distant office 41 comprises a toll 50 operator position 42 of any suitable type; and the remote office 31 comprises a local switch train and toll switching equipment of the automatic type.

In the remote office 31 the local switch train 55 comprises a plurality of local links, including

the local link 344, and a local distributor 343 for distributing idle ones of the local links in a predetermined order; the local link 344 including a local finder 345 and a local connector 346. The toll switching equipment comprises a group of five toll links, including the third toll link 503 illustrated; the third toll link 503 including a toll finder 400 and a toll selector 500. One end of each control trunk terminates in control trunk terminal equipment individual thereto disposed in the central office 21; and the other end of each control trunk terminates in control trunk equipment individual thereto disposed in the remote office 31. For example, one end of the first control trunk 701 terminates in first control trunk terminal equipment 601 individual thereto disposed in the central office 21; and the other end of the first control trunk 701 terminates in first control trunk equipment 901 individual thereto disposed in the remote office 31. Similarly, the opposite ends of the second control trunk 702 terminate in second control trunk terminal equipment 602 and in second control trunk equipment 902 respectively disposed in the central office 21 and in the remote office 31; while the opposite ends of the third control trunk 703 terminate in third control trunk terminal equipment 603 and in third control trunk equipment, not shown, respectively disposed in the central office 21 and in the remote office 31. Finally one end of the supervisory conductor C705 terminates in supervisory equipment 605 disposed in the central office 21; and the other end of the supervisory conductor C705 terminates in common equipment 800 disposed in the remote office 31.

In the remote office 31 the common equipment 800 has access to each of the toll links in the group mentioned and is operative to select an idle toll link therefrom; and each control trunk equipment has access to each of the toll links in the group mentioned and is operative to connect an idle toll link selected by the common equipment 800 thereto and consequently to the associated control trunk when the last-mentioned control trunk is idle. Also each control trunk equipment comprises a monitor switch and a trunk switch, each having access to each of the toll links in the group mentioned, for purposes more fully explained hereinafter. Also the remote office 31 comprises a group of toll line circuits terminating the group of toll lines, this group including the toll line circuit 310 terminating the toll line 301; and a group of C. L. R. trunk circuits terminating an associated group of C. L. R. trunks, this group including the C. L. R. trunk circuit 350 terminating the C. L. R. trunk 390. Also the remote office 31 serves a number of local subscriber substations, including the subscriber substation T, the subscriber substation T having a subscriber line 341 extending thereto which is provided with an individually associated line circuit 342. Further the remote office 31 comprises a signal sender 1000 which is operatively associated with the common equipment 800, for a purpose more fully explained hereinafter.

Each control trunk terminal equipment terminating one end of the associated control trunk in the central office 21 is accessible to each operator position at the control switchboard 200; while each control trunk equipment terminating the other end of the associated control trunk in the remote office 31 has access by way of the individually associated monitor switch and the individually associated trunk switch to each of the toll links in the associated group. One end of

each of the toll lines in the group terminates at the toll operator position 42 in the distant exchange 41; while the other end of each of the toll lines in the group terminates in a corresponding one of the toll line circuits in the remote office 31. Each local finder and each local connector have access to each subscriber line terminating in the remote office 31; while each local connector has access to each of the C. L. R. trunks in the group. The toll finder of each toll link in the group mentioned has access to each of the toll line circuits and to each of the C. L. R. trunk circuits; while the toll selector of each toll link in the group mentioned has access to each of the toll lines in the group and to each of a number of utility trunks, including the utility trunk 591, provided in the remote office 31.

Preferably, each operator position at the control switchboard 200 is identical to the first operator position 201 which comprises, as best shown in Fig. 2, a suitable telephone set 285, a set of position keys, a suitable dial 286, and a group of signal lamps. More particularly, the set of position keys includes a common ring key K215; a common release key K212; three trunk talk keys individual to the three control trunks, the first trunk talk key individual to the first control trunk 701 being indicated at K220; and five link hold keys individual to the five toll links in the group mentioned, the first and third link hold keys, respectively, individual to the first and third toll links in the group mentioned being respectively indicated at K230 and K240. More particularly, the group of signal lamps comprises an answer lamp and a busy lamp individual to each of the control trunks, the answer lamp and the busy lamp individual to the first control trunk 701 being respectively indicated at L256 and L255; and a hold lamp and a supervisory lamp individual to each of the toll links in the group mentioned, the hold lamp and the supervisory lamp individual to the first toll link, not shown, being respectively indicated at L252 and L251, and the hold lamp and the supervisory lamp individual to the third toll link 503 being respectively indicated at L254 and L253.

Preferably, each control trunk terminal equipment is identical to the first control trunk terminal equipment 601 which comprises, as best shown in Fig. 6, a lamp switch 610 of the minor type, including three wipers 611 to 613, inclusive, provided with individually associated contact banks, a rotary magnet M614 for driving the wipers noted step by step in the counterclockwise direction away from their normal rotary positions, and a release magnet M615 for releasing the wipers noted and for causing them to be returned to their normal rotary positions. Also associated with the lamp switch 610 are two sets of switch springs S616 and S617 which are actuated when the wipers noted are moved away from their normal rotary positions. At this point it is noted that the wipers 611, 612 and 613 of the lamp switch 610 have respective access to three groups of conductors respectively extending to the various hold lamps at the respective first, second and third operator positions at the control switchboard 200, for a purpose more fully explained hereinafter. Further the first control trunk terminal equipment 601 comprises a relay group including an impulse relay R620, two hold relays R625 and R630, and an answer relay R640. Finally the first control trunk terminal equipment 601 comprises a repeater 595 terminating the associated end of the first control trunk 701;

and a control network connected and arranged in a manner more fully explained hereinafter.

The supervisory equipment 650 comprises, as best shown in Fig. 6, a lamp switch 660 of the minor type, including a single wiper 661 having an associated contact bank, a rotary magnet M662 for driving the wiper noted step by step in the counterclockwise direction away from its normal rotary position, and a release magnet M663 for releasing the wiper noted and for causing it to be returned to its normal rotary position. Also associated with the lamp switch 660 is a set of switch springs S664 which is actuated when the wiper 661 is driven away from its normal rotary position. Further the supervisory equipment 650 comprises a relay group including an impulse relay R690, a hold relay R685, a hold slave relay R680, and five link lock relays individual to the five toll links in the group mentioned, the first and third link lock relays being respectively indicated at R670 and R675; and a control network connected and arranged in a manner more fully described hereinafter.

The common equipment 800 comprises, as best shown in Figs. 7 and 8, a finder switch 720 of the rotary type, including two wipers 721 and 722 provided with individually associated contact banks, and a rotary magnet M723 for driving the wipers noted step by step in the counterclockwise direction. Also the common equipment 800 comprises a relay group including an all-busy relay R730, a start relay R740, a cutoff relay R750, two sender stop relays R810 and R820, a supervisory start relay R830, a sender start relay R840, an impulse relay R850 and two cycle relays R860 and R870. Finally the common equipment 800 comprises a repeater 710 terminating the associated end of the first control trunk 701; and a control network connected and arranged in a manner more fully explained hereinafter.

Preferably, each control trunk equipment is identical to the first control trunk equipment 901 which comprises, as best shown in Figs. 8 and 9, a monitor switch 880 of the minor type, including three wipers 881 to 883, inclusive, provided with individually associated contact banks, a rotary magnet M884 for driving the wipers noted step by step in the clockwise direction away from their normal rotary positions, and a release magnet M885 for releasing the wipers noted and for causing them to be returned to their normal rotary positions. Also a set of switch springs S886 is associated with the monitor switch 880 which is actuated when the wipers noted are driven away from their normal rotary positions. Also the first control trunk equipment 901 comprises a trunk switch 910 of the rotary type, including five wipers 911 to 915, inclusive, provided with individually associated contact banks, and a rotary magnet M916 for driving the wipers noted step by step in the counterclockwise direction. Finally the first control trunk equipment 901 comprises a relay group including a connect relay R920, a hold relay R930, an impulse relay R940, a release relay R945, a cutoff relay R950, a step relay R955 and a switch start relay R960; and a control network connected and arranged in a manner more fully described hereinafter.

The signal sender 1000 comprises, as best shown in Fig. 10, a relay group including a control relay R1010 and five count relays R1020, R1030, R1040, R1050 and R1060, the various count relays respectively corresponding to the five individual toll links in the group mentioned.

Each subscriber substation in the remote office 31 comprises conventional automatic substation equipment including a telephone instrument, a ringer and a calling device or dial; and the toll operator position 42 in the distant office 41 comprises conventional operator position equipment. Also, in the remote office 31, each of the line circuits 342, etc., as well as the associated local distributor 343, shown in Fig. 3, is of conventional connection and arrangement. Further each of the local finders 345, etc. and each of the local connectors 346, etc., shown in Fig. 3, are of conventional connection and arrangement; preferably, these switches are of the well-known Strowger type.

Preferably, each of the toll line circuits is identical to the toll line circuit 310, shown in Fig. 3, which comprises a relay group, including a ring-up relay R320, a start relay R325 and a cutoff relay R330; and a control network connected and arranged in a manner more fully described hereinafter. Preferably, each of the C. L. R. trunk circuits is identical to the C. L. R. trunk circuit 350, shown in Fig. 3, which comprises a relay group, including a line relay R360, a start relay R370 and a cutoff relay R380, and a repeater 351; and a control network connected and arranged in a manner more fully described hereinafter.

Preferably, each of the toll links is identical to the third toll link 503 shown in Figs. 4 and 5. In the third toll link 503 the toll finder 400 comprises an access switch 410 of the rotary type, including three wipers 401 to 403, inclusive, provided with individually associated contact banks and a rotary magnet M404 for driving the wipers noted step by step in the counterclockwise direction. Also the toll finder 400 comprises a relay group, including a step relay R415, a switch-through relay R420, a supervisory relay R430, an equipment start relay R440, a switch relay R450, and two control relays R460 and R470; and a control network connected and arranged in a manner more fully described hereinafter. In the third toll link 503 the toll selector 500 comprises a switch mechanism 510 of the Strowger type. The switch mechanism 510 comprises a wiper carriage mounted for both vertical and rotary movements and supporting a wiper set including three wipers 511 to 513, inclusive. A semi-cylindrical contact bank is associated with the wiper set and comprises ten vertically spaced-apart rows or levels of contact sets, each row of contact sets including ten individual contact sets arranged in circumferential spaced-apart relationship. Further the switch mechanism 510 comprises a vertical magnet M514 for driving the wiper carriage step by step in the vertical direction away from its normal vertical position, a rotary magnet M515 for driving the wiper carriage step by step in the rotary direction away from its normal rotary position, and a release magnet M517 for releasing the wiper carriage and for causing it to be returned to its normal rotary and vertical positions. Also the switch mechanism 510 comprises three sets of switch springs S519, S520 and S521 which are actuated when the wiper carriage is moved in the vertical direction away from its normal vertical position, and a set of switch springs S522 which is actuated when the wiper carriage is driven eleven steps in the rotary direction away from its normal rotary position. Further the toll selector 500 comprises a relay group, including a control relay R480, a switch-through relay R530, an im-

pulse relay R540, a release relay R545, a hold relay R550, a transfer relay R560, a ring relay R570, and a ring slave relay R580; and a control network connected and arranged in a manner more fully described hereinafter.

While the apparatus incorporated in the telephone system has been described as comprising five toll links disposed in the remote office 31, it will be understood that this number of toll links has been taken for reference purposes and that the actual number of links which may be provided will be determined in accordance with the amount of toll traffic which is to be handled in the remote office 31. Similarly, the actual number of control trunks which will be provided, interconnecting the central office 21 and the remote office 31, will be determined in accordance with the amount of toll traffic which is to be handled at the control switchboard 200. Finally the actual number of operator positions which are provided at the control switchboard 200 will be determined in accordance with operating practice in view of the amount of toll traffic to be handled therat.

A better understanding of the connection and arrangement of the apparatus incorporated in the system will be facilitated from a consideration of the detailed operation of the various pieces of apparatus incident to the setting up of the various toll and trunk calls, as will appear hereinafter.

Initiation of a toll call at a subscriber substation in the remote office

Considering now the initiation of a toll call at a subscriber substation, such, for example, as the subscriber substation T, in the remote office 31, the subscriber at the calling subscriber substation T first removes the receiver of the telephone instrument thereat from its associated switchhook, whereby the line circuit 342 individually associated with the subscriber line 341 operates in order to initiate operation of the associated local distributor 343. The local distributor 343 operates in order to assign an idle one of the local links to the use of the calling subscriber substation T, such, for example, as the local link 344 illustrated. The local finder 345 then operates to find the subscriber line 341 extending to the calling subscriber substation T, whereupon the local connector 346 is rendered responsive to digits transmitted thereto; and the line circuit 342 operates in order to mark the subscriber line 341 as busy to the local connectors having access thereto. The subscriber at the calling subscriber substation T then dials one or more digits into the local connector 346, thereby to cause the local connector 346 to seize an idle C. L. R. trunk in the associated group, such, for example, as the C. L. R. trunk 390; the C. L. R. trunk 390 being marked as idle by the presence of battery potential upon the control conductor C393 thereof via the contacts 373 and the resistor 385. When the C. L. R. trunk 390 is thus seized a series circuit is completed for energizing the upper and lower windings of the line relay R360 in the C. L. R. trunk circuit 350; this circuit extending from ground by way of the upper winding of R360 and the winding 353 of the repeater 351 to the line conductor C392 and from battery by way of the lower winding of R360 and the winding 352 of the repeater 351 to the line conductor C391, the line conductors C391 and C392 of the C. L. R. trunk 390 being connected by way of the local connector 346, the local finder 345 and the sub-

scriber line 341 to the calling subscriber substation T.

When the line relay R360 is thus energized it operates to complete, at the contacts 361, an obvious circuit for energizing the winding of the start relay R370, thereby to cause the latter relay to operate shortly thereafter, the start relay R370 being of the combination slow-to-operate and slow-to-release type. Upon operating, the start relay R370 interrupts, at the contacts 373, the previously traced path for applying battery potential to the control conductor C393 of the C. L. R. trunk 390; and completes, at the contacts 372, an obvious path for applying ground potential to the control conductor C393 of the C. L. R. trunk 390, whereby the latter trunk is marked as busy to the local connectors having access thereto. Also the start relay R370 completes, at the contacts 374, an obvious path for applying battery potential by way of the winding of the cutoff relay R380 to the control conductor C398 of the trunk 395 extending to the C. L. R. trunk circuit 350 and accessible to the toll finders of the various toll links, thereby to mark the trunk 395 as a calling trunk to the toll finders of the various toll links. Further the start relay R370 completes, at the contacts 374, an obvious path, including the contacts 382, for applying ground potential to the start conductor C755 extending to the common equipment 800.

The application of ground potential to the start conductor C755 completes a circuit for energizing the winding of the start relay R140 in the event the common equipment 800 and at least one control trunk equipment are idle at this time; which circuit extends, when completed, from the grounded start conductor C755 by way of the contacts 731, the winding of R740, and the contacts 811, 821 and 832 to battery; whereupon the start relay R740 operates. At this point it is noted that, when the first control trunk equipment 901 is busy due to a busy condition of the first control trunk 701, either the connect relay R920 or the hold relay R930 occupies its operated position, as explained more fully hereinafter. When the connect relay R920 occupies its operated position there is prepared, at the contacts 921, a point in a circuit traced hereinafter for energizing the winding of the all-busy relay R730; and when the hold relay R930 occupies its operated position there is prepared, at the contacts 935, a point in a circuit traced hereinafter for energizing the winding of the all-busy relay R730. Accordingly, when the first control trunk equipment 901 is busy the conductor C867 extending to the winding of the all-busy relay R730 in the common equipment 800 is connected by way of the contacts 927 or 935 of the respectively associated relay R920 or R930 in the first control trunk equipment 901 to the conductor C936 extending to the second control trunk equipment 902. Hence it will be understood that, when each of the three control trunk equipments is busy, the previously mentioned chain circuit, including the conductors C867 and C936, is completed for energizing the winding of the all-busy relay R730; whereupon the latter relay operates to interrupt, at the contacts 731, a point in the previously traced circuit for energizing the winding of the start relay R740. In the last-mentioned event, the application of ground potential to the start conductor C755 is ineffective to cause operation of the start relay

R740 until one of the three control trunk equipments becomes idle in an obvious manner.

Continuing now with the operation of the common equipment 800, when the start relay R740 operates it completes, at the contacts 742, an obvious holding circuit, including the contacts 731, 811, 821 and 832, for energizing the winding thereof. Also, upon operating, the start relay R740 prepares, at the contacts 743, a circuit for energizing the rotary magnet M723 of the finder switch 720; the last-mentioned circuit extending from the wiper 722 of the finder switch 720 by way of the contacts 752, 743 and 724 and the rotary magnet M723 to battery. The above-mentioned circuit for energizing the rotary magnet M723 is completed in the event the wiper 722 of the finder switch 720 engages a contact in the associated contact bank terminating a test conductor having ground potential thereon extending to a busy toll link in the associated group. Assuming that the fifth toll link in the associated group is busy at this time, ground potential appears upon the test conductor thereof, whereby the above-traced circuit for energizing the rotary magnet M723 is completed. When thus energized the rotary magnet M723 operates, thereby to condition the wipers noted of the finder switch 720 to be driven one step in the counterclockwise direction and to interrupt, at the contacts 724, the above-traced circuit for energizing the rotary magnet M723. The rotary magnet M723 then restores, thereby to drive the wipers noted of the finder switch 720 one step in the counterclockwise direction and to re-prepare, at the contacts 724, the above-traced circuit for energizing the rotary magnet M723. At this time the wipers noted of the finder switch 720 engage the first contacts in the associated contact banks, whereby the idle or busy condition of the first toll link in the associated group is tested. Further operation of the finder switch 720 continues until an idle toll link in the associated group is tested.

Assuming that the third toll link 503 illustrated is the first idle toll link in the group, the rotary magnet M723 continues to operate intermittently until the wiper 722 thereof engages the contact in the associated contact bank terminating the test conductor C766 individual to the idle third toll link 503, the test conductor C766 having battery potential applied thereto by way of the winding of the equipment start relay R440 and the contacts 427. Also, it is noted that, upon operating, the start relay R740 completes, at the contacts 744, a path, including the contacts 743 and 752 and the wiper 722, for short-circuiting the winding of the cutoff relay R750 as long as the wiper 722 engages a contact in the associated contact bank having ground potential thereon. In the present example, when the wiper 722 of the finder switch 720 engages the contact in the associated contact bank terminating the test conductor C766 having battery potential thereon, the above-mentioned path for short-circuiting the winding of the cut-off relay R750 is interrupted; whereupon a series circuit is completed for energizing the winding of the cutoff relay R750 and the rotary magnet M723 of the finder switch 720 and a multiple series circuit is completed for energizing the winding of the cutoff relay R750 and the winding of the equipment start relay R440. The circuits mentioned extend from ground by way of the contacts 744, the winding of R750, the contacts 724 and the rotary magnet M723 to battery; and 75

from ground by way of the contacts 744, the winding of R750, the contacts 743 and 752, the wiper 722 of the finder switch 720 and the engaged contact in the associated contact bank, C766, the contacts 427 and the winding of R440 to battery. When the circuits mentioned are completed the cutoff relay R750 operates. However, the equipment start relay R440 and the rotary magnet M723 do not operate due to the high series resistance of the winding of the cutoff relay R750. Accordingly further operation of the finder switch 720 is arrested at this time. Upon operating, the cutoff relay R750 interrupts, at the contacts 752, the previously traced series circuit for energizing the winding of the cutoff relay R750 and the winding of the equipment start relay R440; however, the cutoff relay R750 remains in its operated position due to the previously completed holding circuit for energizing the winding thereof in series with the rotary magnet M723. Also the cutoff relay R750 completes, at the contacts 753, an alternative circuit, including the wiper 722 of the finder switch 720 and the engaged contact in the associated contact bank, C766 and the contacts 427, for energizing the winding of the equipment start relay R440, whereupon the latter relay operates. Upon operating, the equipment start relay R440 completes, at the contacts 445, a holding circuit for energizing the winding thereof; the last-mentioned circuit including the contacts 751, the wiper 721 of the finder switch 720 and the engaged contact in the associated contact bank, and the hold conductor C765. Accordingly, at this time, the common equipment 800 has operated to select the idle third toll link 503 in the associated group to the use of the calling trunk 395 extending to the C. L. R. trunk circuit 350 connected to the calling subscriber substation T.

Continuing now with the operation of the third toll link 503, upon operating, the equipment start relay R440 completes, at the contacts 441, an obvious path for applying ground potential to the hold conductor C485, thereby to complete an obvious circuit, including the resistor 417, for energizing the lower winding of the switch-through relay R420 in the toll finder 400. When the lower winding of the switch-through relay R420 is thus energized the latter relay is rendered exceedingly fast to operate when the upper winding thereof is subsequently energized. Also the application of ground potential to the hold conductor C485 completes an obvious circuit, including the contacts 482 and the set of switch springs S520, for energizing the upper winding of the transfer relay R560 in the toll selector 500, thereby to cause the latter relay to operate. Further the equipment start relay R440 completes, at the contacts 447, an obvious circuit for energizing the lower winding of the supervisory relay R430, thereby to cause the latter relay to operate and interrupt, at the contacts 431, an obvious path for short-circuiting the upper winding thereof.

Also the application of ground potential to the hold conductor C485 completes a circuit, including the contacts 426 and 416, for energizing the rotary magnet M404 of the access switch 410, thereby to cause the latter magnet to operate. Upon operating, the rotary magnet M404 conditions the wipers noted of the access switch 410 to be driven one step in the counterclockwise direction; and completes, at the contacts 405, an obvious circuit for energizing the winding of the step relay R415, thereby to cause the latter relay

to operate. Upon operating, the step relay R415 interrupts, at the contacts 416, the previously traced circuit for energizing the rotary magnet M404, whereupon the latter magnet restores. Upon restoring, the rotary magnet M404 drives the wipers noted of the access switch 410 one step in the counterclockwise direction and interrupts, at the contacts 405, the previously mentioned circuit for energizing the winding of the step relay R415, whereupon the latter relay restores. Accordingly the rotary magnet M404 and the step relay R415 interact, in the manner described above, whereby the wipers noted of the access switch 410 are driven step by step in the counterclockwise direction until they engage the contacts in the associated contact bank terminating the trunk 395 extending to the calling C. L. R. trunk circuit 350.

When the access switch 410 finds the trunk 395 extending to the calling C. L. R. trunk circuit 350 a circuit for energizing in series the upper winding of the supervisory relay R430, the upper winding of the switch-through relay R420 and the winding of the cutoff relay R380 is completed; the last-mentioned circuit extending from the grounded hold conductor C485 by way of the upper winding of R430, the upper winding of R420, the wiper 403 of the access switch 410 and the engaged contact in the associated contact bank, the control conductor C398 of the trunk 395, the contacts 371 and the winding of R380 to battery. When this series circuit is completed the supervisory relay R430 is retained in its operated position and the switch-through relay R420 operates exceedingly fast as it is of the polarized type, as previously noted. Upon operating, the switch-through relay R420 completes, at the contacts 424, an obvious path in the above-traced series circuit for short-circuiting the upper winding thereof; whereby the upper winding of the supervisory relay R430 is energized in series with the winding of the cutoff relay R380, in an obvious manner. The cutoff relay R380 then operates to complete, at the contacts 381, an obvious multiple point around the contacts 371 in the previously traced circuit for energizing the winding thereof in series with the upper winding of the supervisory relay R430. Also, upon operating, the cutoff relay R380 interrupts, at the contacts 382, the previously traced original path for applying ground potential in the C. L. R. trunk circuit 350 to the start conductor C155 extending to the common equipment 800.

Also, upon operating, the switch-through relay R420 interrupts, at the contacts 426, a point in the previously traced circuit for energizing the rotary magnet M404, thereby positively to arrest further operation of the access switch 410 at this time. Also the switch-through relay R420 completes, at the contacts 423, an obvious multiple path for applying ground potential to the hold conductor C485; and completes, at the contacts 425, an obvious multiple holding circuit for energizing the intermediate winding thereof. Also the switch-through relay R420 interrupts, at the contacts 427, the original circuit for energizing the winding of the equipment start relay R440; however, the latter relay remains in its operated position at this time due to the completed holding circuit for energizing the winding thereof, including the hold conductor C165. Further the switch-through relay R420 completes, at the contacts 428, an obvious path for applying ground potential to the test conductor C766 extending to the finder switch 720, thereby positively to

mark the third toll link 503 as busy to the common equipment 800. Further the switch-through relay R420 completes, at the contacts 422, an obvious circuit for energizing the winding of the switch relay R450, thereby to cause the latter relay to operate. Upon operating, the switch relay R450 completes, at the contacts 452, an obvious circuit for energizing the winding of the control relay R470, thereby to cause the latter relay to operate. Also, upon operating, the switch relay R450 completes, at the contacts 453, an obvious path, including the contacts 446, for applying ground potential to the chain start conductor C862 extending to the first control trunk equipment 901 and therethrough to the other control trunk equipments, in a manner more fully explained hereinafter.

Upon operating, the control relay R470 completes, at the contacts 472, an obvious path for applying battery potential by way of the winding of the control relay R460 to the test conductor C985 and an obvious multiple path for applying battery potential by way of the resistor 466 and the contacts 463 to the test conductor C985. Also the control relay R470 completes, at the contacts 471, an obvious path for applying ground potential to the control conductor C984. The application of battery potential to the test conductor C985 marks the third toll link 503 as a calling link to the trunk switches of the various control trunk equipments; while the application of ground potential to the control conductor C984 prepares the third toll link 503 to be connected to the control trunk associated with an idle one of the control equipments, all in a manner more fully explained hereinafter.

Considering now the operation of the various control trunk equipments in response to the application of ground potential to the chain start conductor C862, it is pointed out that the application of ground potential to the chain start conductor C862 completes a circuit, including the contacts 933 and 934, for energizing the winding of the switch start relay R960 in the first control trunk equipment 901 in the event the associated first control trunk 781 is idle at this time; in which event the hold relay R930 and the cutoff relay R950 in the first control trunk equipment 901 occupy their restored positions. Also the application of ground potential to the chain start conductor C862 is connected by way of the contacts 964 of the restored switch start relay R960 in the first control trunk equipment 901 to the conductor C980 extending to the second control trunk equipment 902; whereby a multiple circuit substantially identical to that traced above is prepared for energizing the winding of the switch start relay in the second control trunk equipment 902. Further it is noted that the application of ground potential to the chain start conductor C862 is similarly extended from the second control trunk equipment 902 to the third control trunk equipment, not shown, in order to prepare a further multiple circuit for energizing the winding of the switch start relay in the third control trunk equipment. Accordingly it will be understood that the application of ground potential to the chain start conductor C862 prepares multiple circuits for energizing the windings of the switch start relays in the various control trunk equipments; and that the circuit for energizing the winding of the switch start relay in each idle control trunk equipment is completed. At this point it is noted that the various switch start relays R960 etc. in the corresponding control

trunk equipments are of the slow-to-operate type; and that these switch start relays are graduated progressively in their slow-to-operate characteristic; whereby the first idle control trunk equipment 901 in the chain is preferred. In other words, the switch start relay R960 in the first control trunk equipment 901 is slightly faster to operate than the switch start relay in the second control trunk equipment 902, and the switch start relay in the second control trunk equipment 902 is slightly faster to operate than the switch start relay in the third control trunk equipment, not shown.

Assuming that the first control trunk equipment 901 is idle at this time, the application of ground potential to the chain start conductor C862 completes the above-traced circuit for energizing the winding of the switch start relay R960, whereby the latter relay operates shortly thereafter; the switch start relay R960 in the first control trunk equipment 901 being slightly faster to operate than the corresponding switch start relays in the second and third control trunk equipments, as previously noted. Upon operating, the switch start relay R960 completes, at the contacts 963, an obvious holding circuit, including the grounded chain start conductor C862, for energizing the winding thereof; and interrupts, at the contacts 964, the previously traced connection between the grounded chain start conductor C862 and the conductor C980 extending to the second control trunk equipment 902; whereby the initiation of operation of the second and third control trunk equipments is effectively cut off, in an obvious manner.

Also, upon operating, the switch start relay R960 completes, at the contacts 962, an obvious circuit, including the contacts 952 and 956, for energizing the rotary magnet M916 of the trunk switch 910. When thus energized the rotary magnet M916 operates to condition the wipers noted of the trunk switch 910 to be driven one step in the counterclockwise direction and to complete, at the contacts 917, an obvious circuit for energizing the lower winding of the step relay R955, whereby the latter relay operates. Upon operating, the step relay R955 interrupts, at the contacts 956, the previously traced circuit for energizing the rotary magnet M916, thereby to cause the latter magnet to restore in order to drive the wipers noted of the trunk switch 910 one step in the counterclockwise direction and to interrupt, at the contacts 917, the previously mentioned circuit for energizing the lower winding of the step relay R955, whereupon the latter relay restores. Accordingly the rotary magnet M916 and the step relay R955 interact in the manner described above until the wipers noted of the trunk switch 910 engage the contacts in the associated contact bank terminating the conductors extending to the third toll link 503. More particularly, when the wiper 915 of the trunk switch 910 engages the contact in the associated contact bank terminating the test conductor C985 extending to the third toll link 503, a series circuit is completed for energizing the lower winding of the cutoff relay R950, the upper winding of the step relay R955 and the winding of the control relay R460; this circuit extending from ground by way of the lower winding of R950, the upper winding of R955, the contacts 961, the wiper 915 of the trunk switch 910 and the engaged contact in the associated contact bank, C985, the contacts 472 and the winding of R460 to battery. When this series circuit is completed

the step relay R955 is retained in its operated position and the cutoff relay R950 operates; and shortly thereafter the control relay R460 operates, the latter relay being of the slow-to-operate type.

- Upon operating, the cutoff relay R950 interrupts, at the contacts 952, a further point in the previously traced circuit for energizing the rotary magnet M916, thereby positively to arrest further operation of the trunk switch 910 at this time; and interrupts, at the contacts 953, a further point in the previously traced original circuit for energizing the winding of the switch start relay R960, thereby to mark the first control trunk equipment 901 as busy at this time. Also when the wiper 914 of the trunk switch 910 engages the contact in the associated contact bank terminating the grounded control conductor C984 extending to the third toll link 503 an obvious circuit, including the contacts 932, is completed for energizing the winding of the connect relay R920, thereby to cause the latter relay to operate. Also, upon operating, the cutoff relay R950 completes, at the contacts 951, an obvious holding circuit, including the wiper 914 of the trunk switch 910 and the engaged contact in the associated contact bank and the grounded control conductor C984, for energizing the upper winding thereof.
- Upon operating, the connect relay R920 interrupts, at the contacts 923 and 925, a normally completed connection between the winding 712 of the repeater 710 and the wipers 883 and 882 of the monitor switch 880; and completes, at the contacts 924 and 926, an obvious connection between the winding 712 of the repeater 710 and the wipers 912 and 913 of the trunk switch 910. More particularly, at this time, the repeater 710 terminating the end of the first control trunk 701 in the remote office 31 is operatively connected to the repeater 351 in the C. L. R. trunk circuit 350; the winding 712 of the repeater 710 is connected by way of the conductors C762 and C763 and the contacts 924 and 926 to the wipers 912 and 913 of the trunk switch 910; the wiper 912 of the trunk switch 910 is connected by way of the engaged contact in the associated contact bank, C982 and the contacts 451 to the wiper 402 of the access switch 410; the wiper 913 of the trunk switch 910 is connected by way of the engaged contact in the associated contact bank, C983 and the contacts 421 to the wiper 401 of the access switch 410; and the wiper 402 of the access switch 410 is connected by way of the engaged contact in the associated contact bank, the line conductor C397 of the trunk 395, the winding 355 of the repeater 351, the condenser 357, the winding 354 of the repeater 351 and the line conductor C396 of the trunk 395 to the contact engaged by the wiper 401 of the access switch 410. Also, upon operating, the connect relay R920 interrupts, at the contacts 921, an obvious connection including the conductor C761 between the simplex of the winding 711 of the repeater 710 and the windings of the impulse relay R940 and the release relay R945; and completes, at the contacts 922, a connection between the simplex of the winding 711 of the repeater 710 and the code conductor C863 extending to the common equipment 800. More particularly, the simplex of the winding 711 of the repeater 710 is connected by way of the conductor C761, the contacts 922, the wiper 911 of the trunk switch 910 and the engaged contact in the associated contact

bank, C981 and the contacts 444 to the code conductor C863 extending to the common equipment 888. Finally the connect relay R920 prepares, at the contacts 927, a further point in the previously traced chain circuit for energizing the winding of the all-busy relay R730, for the purpose previously explained.

Accordingly, at this time, the first control trunk equipment 901 has been selected for use by the chain start arrangement described above; the trunk switch 910 of the first trunk control equipment 901 has operated to seize the third toll link 503; and the connect relay R920 has operated to connect the trunk switch 910 to the first control trunk 701 extending to the remote office 31 and the central office 21.

Upon operating, the control relay R460 interrupts, at the contacts 463, the previously traced path for applying battery potential by way of the resistor 466 to the test conductor C985; and completes, at the contacts 462, an obvious alternative holding circuit, including the contacts 564, for energizing the winding thereof. Also the control relay R460 completes, at the contacts 462, an obvious path, including the contacts 564 and 472, for applying ground potential to the test conductor C985, thereby positively to mark the third toll link 503 as busy to the trunk switches of the second and third control trunk equipments. Also the control relay R460 completes, at the contacts 461, an obvious multiple path for applying ground potential to the control conductor C984, thereby to complete an obvious multiple holding circuit for energizing the winding of the connect relay R920 and the upper winding of the cutoff relay R958 in order to retain the latter relays in their operated positions. Further the control relay R460 completes, at the contacts 464, an obvious path, including the contacts 448, for applying ground potential to the start conductor C764 extending to the common equipment 888; and completes, at the contacts 465, an obvious path, including the contacts 449 and the resistor 467, for applying battery potential to the third marking conductor C865 individual to the third toll link 503 and extending to the signal sender 1000.

The application of ground potential to the start conductor C764 completes an obvious circuit, including the contacts 741, for energizing the winding of the sender start relay R840, thereby to cause the latter relay to operate. Upon operating, the sender start relay R840 completes, at the contacts 842, an obvious circuit, including the contacts 814, 824 and 861, for energizing the winding of the cycle relay R870, thereby to cause the latter relay to operate. Upon operating, the cycle relay R870 completes, at the contacts 872, an obvious holding circuit, including the contacts 861, for energizing the winding thereof; and completes, at the contacts 871, an obvious circuit for energizing the winding of the impulse relay R850. When thus energized the impulse relay R850 operates to complete, at the contacts 851, an obvious circuit for energizing the winding of the cycle relay R860, thereby to cause the latter relay to operate. Upon operating, the cycle relay R860 interrupts, at the contacts 861, the previously traced holding circuit for energizing the winding of the cycle relay R870, thereby to cause the latter relay to restore. Upon restoring, the cycle relay R870 interrupts, at the contacts 872, a further point in the previously traced holding circuit for energizing the winding thereof; and interrupts, at the contacts 871, the previously

mentioned circuit for energizing the winding of the impulse relay R850, thereby to cause the latter relay to restore. Upon restoring, the impulse relay R850 interrupts, at the contacts 851, the previously mentioned circuit for energizing the winding of the cycle relay R860, thereby to cause the latter relay to restore. Upon restoring, the cycle relay R860 recompletes, at the contacts 861, the previously traced original circuit for energizing the winding of the cycle relay R870, thereby to cause the latter relay to re-operate. Accordingly the cycle relay R870, the impulse relay R850 and the cycle relay R860 interact in the manner described above; whereby the impulse relay R850 is operated and restored intermittently one or more times until operation of the relays mentioned is arrested, in a manner more fully explained below.

Each time the impulse relay R850 operates and restores it completes and then interrupts, at the contacts 853, an obvious path for applying ground potential to the conductor C1071 extending to the signal sender 1000; and completes and then interrupts, at the contacts 854, an obvious path, including the contacts 814, 824 and 843, for applying ground potential to the conductor C1072 extending to the signal sender 1000. Also at this time ground potential is applied by way of the contacts 814, 824 and 842 to the conductor C1073 extending to the signal sender 1000. The first time ground potential is connected to the conductor C1071 an obvious path, including the contacts 1011 and the grounded conductor C1073, is completed for short-circuiting the lower winding of the control relay R1010; and the first time ground potential is connected to the conductor C1072 a circuit, including the contacts 1063, 1054, 1044, 1034 and 1024, is completed for energizing the winding of the first count relay R1020. When thus energized the first count relay R1020 operates to prepare, at the contacts 1021, a holding circuit traced hereinafter for energizing the winding thereof in series with the lower winding of the control relay R1010; prepares, at the contacts 1022, a circuit traced hereinafter for energizing the winding of the second count relay R1030; completes, at the contacts 1023, an obvious holding circuit, including the contacts 1014 and the grounded conductor C1072, for energizing the winding thereof; and interrupts, at the contacts 1024, the previously traced original operating circuit for energizing the winding thereof.

The first time ground potential is disconnected from the conductor C1072 the previously traced holding circuit for energizing the winding of the first count relay R1020 is interrupted; and the first time ground potential is disconnected from the conductor C1071 the previously traced path for short-circuiting the lower winding of the control relay R1010 is interrupted. At this time the previously mentioned holding circuit for energizing the winding of the first count relay R1020 in series with the lower winding of the control relay R1010 is completed and extends from the grounded conductor C1073 by way of the lower winding of R1010, the contacts 1031 and 1021 and the winding of R1020 to battery. When this holding circuit is completed the first count relay R1020 is retained in its operated position and the control relay R1010 operates. Upon operating, the control relay R1010 interrupts, at the contacts 1011, a further point in the previously traced path for short-circuiting the lower winding thereof; prepares, at the contacts 1012, a

circuit traced hereinafter for energizing the upper winding thereof; interrupts, at the contacts 1014, a point in a circuit traced hereinafter for energizing the winding of the third count relay R1040; and prepares, at the contacts 1013, a further point in the previously mentioned circuit for energizing the winding of the second count relay R1030.

The second time ground potential is connected to the conductor C1071 an obvious circuit is completed for energizing the upper winding of the control relay R1010; and the second time ground potential is connected to the conductor C1072 the previously mentioned circuit, including the contacts 1013 and 1022, is completed for energizing the winding of the second count relay R1030. When thus energized the second count relay R1030 operates to complete, at the contacts 1032, an obvious holding circuit, including the contacts 1041 and the grounded conductor C1073, for energizing the winding thereof. Also the second count relay R1030 interrupts, at the contacts 1031, the previously traced holding circuit for energizing the winding of the first count relay R1020 in series with the lower winding of the control relay R1010, thereby to cause the first count relay R1020 to restore; the control relay R1010 remaining in its operated position due to the completed holding circuit for energizing the upper winding thereof. Further the count relay R1030 prepares, at the contacts 1033, a point in a circuit traced hereinafter for energizing the winding of the third count relay R1040; and interrupts, at the contacts 1034, a further point in the previously traced original circuit for energizing the winding of the first count relay R1020. Upon restoring, the first count relay R1020 interrupts, at the contacts 1021, a further point in the previously traced holding circuit for energizing the winding thereof in series with the lower winding of the control relay R1010; interrupts, at the contacts 1022, the previously traced original operating circuit for energizing the winding of the second count relay R1030; interrupts, at the contacts 1023, a further point in the previously traced original holding circuit for energizing the winding of the first count relay R1020; and prepares, at the contacts 1024, a further point in the previously traced original circuit for energizing the winding of the first count relay R1020.

The second time ground potential is disconnected from the conductor C1071 the previously traced holding circuit for energizing the upper winding of the control relay R1010 is interrupted, thereby to cause the latter relay to restore. Upon restoring, the control relay R1010 interrupts, at the contacts 1012, a further point in the previously traced holding circuit for energizing the upper winding thereof; prepares, at the contacts 1011, a further point in the previously traced original path for short-circuiting the lower winding thereof; interrupts, at the contacts 1013, a further point in the previously traced circuit for energizing the winding of the second count relay R1030; and prepares, at the contacts 1014, a point in the previously mentioned circuit for energizing the winding of the third count relay R1040.

In view of the foregoing explanation of the mode of operation of the control relay R1010 in conjunction with the first count relay R1020 and the second count relay R1030 in the signal sender 1000, it will be understood that the five

count relays R1020, R1030, R1040, R1050 and R1060 are successively operated in response to a corresponding number of operations of the impulse relay R850 in the common equipment 800.

As the count relays R1020, R1030, etc., in the signal sender 1000 operate sequentially the corresponding toll links in the associated group are tested in order to determine which of the toll links mentioned is connected at this time to the trunk switch 910 of the first control trunk equipment 901 and consequently to the first control trunk 701 extending between the remote office 31 and the central office 21. Hence, in the present example, when the third count relay R1040 is operated the third toll link 503 is tested as connected via the trunk switch 910 of the first control trunk equipment 901 to the first control trunk 701. More particularly, when the third count relay R1040 operates it completes, at the contacts 1045, a circuit for energizing the winding of the sender stop relay R810; the last-mentioned circuit extending from ground by way of the winding of R810, the contacts 754 and 1045, the third marking conductor C865 individual to the third toll link 503, the contacts 449 and 465 and the resistor 467 to battery. When thus energized the sender stop relay R810 operates to complete, at the contacts 812, an obvious holding circuit, including the contacts 841 and the resistor 844, for energizing the winding thereof. Also the sender stop relay R810 interrupts, at the contacts 814, the previously traced circuit for energizing the winding of the cycle relay R870, thereby to cause the latter relay to restore and remain restored; whereby the impulse relay R850 and the cycle relay R860 are restored and remain restored. Also the sender stop relay R810 interrupts, at the contacts 814, the previously traced path for applying ground potential to the conductor C1073; and the impulse relay R850 interrupts, at the contacts 853 and 854, the previously traced paths for applying ground potential to the conductors C1071 and C1072. When ground potential is removed from the conductors C1071, C1072 and C1073 extending to the signal sender 1000 the control relay R1010 and the operated one of the count relays R1020, R1030 etc. restore.

Accordingly, in the present example, the impulse relay R850 operates and then restores three times under the control of the signal sender 1000 in view of the fact that the third toll link 503 in the associated group is connected to the first control trunk 701 extending between the remote office 31 and the central office 21, as explained above. Each time the impulse relay R850 operates and restores it completes and then interrupts, at the contacts 852, an obvious path, including the resistor 845 and the contacts 833, for applying battery potential to the code conductor C863 which is connected by way of the previously traced path to the simplex of the winding 711 of the repeater 710. Accordingly, in the present example, three battery impulses are transmitted over the code conductor C863 to the simplex of the winding 711 of the repeater 710. The three battery impulses transmitted to the simplex of the winding 711 of the repeater 710 are conducted over the two line conductors in parallel over the first control trunk 701 to the simplex of the winding 697 of the repeater 695; and therefrom by way of C698, the contacts 642 and the winding of the impulse relay R620 to ground. Accordingly the impulse relay R620 in the first control trunk terminal

equipment 601 in the central office 21 operates and then restores three times.

Also, upon operating, the sender stop relay R810 interrupts, at the contacts 811, the previously traced holding circuit for energizing the winding of the start relay R740, thereby to cause the latter relay to restore. Upon restoring, the start relay R740 interrupts, at the contacts 742, a further point in the previously traced holding circuit for energizing the winding thereof; and interrupts, at the contacts 744, the previously traced holding circuit for energizing the winding of the cutoff relay R750 in series with the rotary magnet M723 of the finder switch 720 in order to cause the cutoff relay R750 to restore. Upon restoring, the cutoff relay R750 interrupts, at the contacts 751, the previously traced holding circuit for energizing the winding of the equipment start relay R440 in order to cause the latter relay to restore. Upon restoring, the equipment start relay R440 interrupts, at the contacts 441, the previously traced original path for applying ground potential to the hold conductor C485; and interrupts, at the contacts 442, the previously mentioned circuit for energizing the winding of the control relay R470, thereby to cause the latter relay to restore. Also the equipment start relay R440 interrupts, at the contacts 444, the previously traced connection between the code conductor C863 and the simplex of the winding 711 of the repeater 710; and completes, at the contacts 443, the previously mentioned connection between the windings of the impulse relay R540 and the release relay R545 and the simplex of the winding 711 of the repeater 710. Accordingly, at this time, ground potential is connected by way of the winding of the release relay R545, the winding of the impulse relay R540, the contacts 443, C981, the wiper 911 of the trunk switch 910 and the engaged contact in the associated contact bank, the contacts 922 and C761 to the simplex of the winding 711 of the repeater 710, for a purpose more fully explained hereinafter. Further the equipment start relay R440 interrupts, at the contacts 446, the previously traced path for applying ground potential to the chain start conductor C862; thereby to interrupt the previously traced holding circuit for energizing the winding of the switch start relay R860 in the first control trunk equipment 801, whereupon the switch start relay R860 restores. Also the equipment start relay R440 interrupts, at the contacts 447, the previously mentioned circuit for energizing the lower winding of the supervisory relay R430; however, the latter relay remains in its operated position at this time due to the completed holding circuit for energizing the upper winding thereof in series with the winding of the cutoff relay R380 in the C. L. R. trunk circuit 350. Further the equipment start relay R440 interrupts, at the contacts 448, the previously traced path for applying ground potential to the start conductor C754, thereby to interrupt a further point in the previously traced circuit for energizing the winding of the sender start relay R840; the sender start relay R840 then restores shortly thereafter as it is of the slow-to-release type. Finally the equipment start relay R440 interrupts, at the contacts 449, the previously traced path for applying battery potential to the third marking conductor C885 individual to the third toll link 583 and extending to the signal sender 1000.

Upon restoring, the switch start relay R860

interrupts, at the contacts 963, a further point in the previously traced holding circuit for energizing the winding thereof; and recomplete, at the contacts 964, the previously mentioned connection between the chain start conductor C862 and the conductor C980 extending to the second control trunk equipment 902; whereby the second and third control trunk equipments are rendered available to the use of the next calling toll links in the associated group. Also the switch start relay R860 interrupts, at the contacts 961, a previously completed path for short-circuiting the lower winding of the cutoff relay R950 in series with the upper winding of the step relay R955. The last-mentioned path was completed incident to the operation of the control relay R460, previously explained, and extended, when completed, from ground by way of the contacts 564, 462 and 472, C985, the wiper 915 of the trunk switch 910 and the engaged contact in the associated contact bank, the contacts 961, the upper winding of R955 and the lower winding of R950 to ground. When the above-mentioned path for short-circuiting the lower winding of the cutoff relay R950 in series with the step relay R955 was completed incident to the operation of the control relay R460, the step relay R955 restored; however, the cutoff relay R950 remained in its operated position due to the previously completed holding circuit for energizing the upper winding thereof. Upon restoring, the sender start relay R840 interrupts, at the contacts 841, the previously traced holding circuit for energizing the winding of the sender stop relay R810, thereby to cause the latter relay to restore. Upon restoring, the sender stop relay R810 reprepares, at the contacts 811, the previously traced circuit for energizing the winding of the start relay R740.

Accordingly, at this time, the common equipment 800 is completely released and available for further use; the first control trunk equipment 801 is busy, the connect relay R820 and the cutoff relay R850 therein occupying their operated positions; the second and third control trunk equipments are rendered available to the use of calling toll links in the associated group; the signal sender 1000 is completely released; and the third toll link 583 is operatively connected via the trunk switch 910 of the first control trunk equipment 801 to the first control trunk 701 extending between the remote office 31 and the central office 21.

In the first control trunk terminal equipment, each time the impulse relay R620 operates and restores it completes and then interrupts, at the contacts 621, an obvious circuit for energizing the winding of the hold relay R625, thereby to cause the latter relay to operate; the hold relay R625 remains operated during impulsing as it is of the slow-to-release type. Also each time the impulse relay R620 operates and restores it completes and then interrupts, at the contacts 622, an obvious circuit for energizing the rotary magnet M614, whereby the latter magnet operates and restores. Hence, in the present example, the rotary magnet M614 is operated and restored three times, thereby to drive the wipers noted of the lamp switch 610 into engagement with the third contacts in the associated contact banks. At this time the wipers 611, 612 and 613 respectively select the conductors extending to the first, second and third operator positions at the control switchboard 200 and associated with the corre-

sponding third link hold keys K240 etc. at the three operator positions mentioned, for a purpose more fully explained hereinafter. Upon operating, the hold relay R625 completes, at the contacts 626, an obvious circuit for illuminating the first trunk busy lamps L255 etc. at the three operator positions at the control switchboard 200 corresponding to the first control trunk 701 in order to indicate to the operators thereat that the first control trunk 701 is busy at this time. When the wipers noted of the lamp switch 610 are driven away from their normal rotary positions the sets of switch springs S616 and S617 are actuated, thereby respectively to prepare circuits traced hereinafter for illuminating the first trunk answer lamps L256 etc. at the three operator positions at the control switchboard 200 and to prepare a circuit traced hereinafter for energizing the release magnet M615 of the lamp switch 610.

Shortly after the impulse relay R620 restores the third time, the hold relay R625 restores, the latter relay being of the slow-to-release type. Upon restoring, the hold relay R625 completes, at the contacts 627, the previously mentioned circuit, including the contacts 643 and the set of switch springs S616, for illuminating the first trunk answer lamps L256 etc. at the three operator positions at the control switchboard 200 in order to indicate to the operators thereat that the first control trunk 701 has a call thereon from the remote office 31 which requires answering.

The operator at one of the operator positions at the control switchboard 200 answers the call by operating the individually associated first trunk talk key thereof. For example, assuming that the call on the first control trunk 701 is to be answered at the first operator position 201 at the control switchboard 200, the operator thereat operates the first trunk talk key K220 individual to the first control trunk 701. When the first trunk talk key K220 at the first operator position 201 is thus operated there is completed, at the contacts 223 and 226 thereof, an obvious circuit between the telephone set 205 at the first operator position 201 and the winding 696 of the repeater 695. Accordingly, at this time, an operative connection is completed between the first operator position 201 at the control switchboard 200 in the central office 21 and the calling subscriber substation T in the remote office 31. More particularly, the telephone set 205 at the first operator position 201 is operatively connected to the winding 696 of the repeater 695; the winding 697 of the repeater 695 is operatively connected to the winding 711 of the repeater 710 by way of the first control trunk 701; the winding 712 of the repeater 710 is operatively connected by way of the trunk switch 910 in the first control trunk equipment 901, the toll finder 400 of the third toll link 503 and the trunk 395 to the windings 354 and 355 of the repeater 351 in the C. L. R. trunk circuit 350; and the windings 352 and 353 of the repeater 351 in the C. L. R. trunk circuit 350 are operatively connected by way of the C. L. R. trunk 390, the local link 344 and the subscriber line 341 to the calling subscriber substation T. Accordingly the subscriber at the calling subscriber substation T in the remote office 31 may converse with the operator at the first operator position 201 at the control switchboard 200 in the central office 21 and advise the operator concerning the extension of the call.

Also when the first trunk talk key K220 is thus operated there is completed, at the contacts 222 thereof, an obvious path for applying ground po-

70 tential to the conductor G291 extending to the interrupter 26; whereby operation of the interrupter 26 is initiated to cause ground potential to be applied intermittently to the conductor C292 extending therefrom, thereby to complete a circuit, including the contacts 221 of the first trunk talk key K220, the wiper 611 of the lamp switch 610 and the engaged third contact in the associated contact bank and the contacts 242 of the third link hold key K240, for flashing the third link hold lamp L254 at the first operator position 201. The flashing of the third link hold lamp L254 indicates to the operator at the first operator position 201 that the connection which is being answered is routed over the first control trunk 701 via the third toll link 503 in the remote office 31, whereby the toll link utilized in routing the call being answered is thus identified. The operator at the first operator position 201 then operates the third link hold key K240 which is of the locking type; thereby to interrupt, at the contacts 242 thereof, the previously traced circuit for flashing the third link hold lamp L254 and to complete, at the contacts 243 thereof, an obvious circuit for steadily illuminating the third link hold lamp L254. Also when the third link hold key K240 is thus operated there is prepared, at the contacts 241 thereof, a circuit traced hereinafter for illuminating the third link supervisory lamp L253. The illumination of the third link hold lamp L254 at the first operator position 201 indicates to the operator thereat that the supervision of the call which is to be set up via the third toll link 503 in the remote office 31 is to be handled at the first operator position 201, in a manner more fully explained hereinafter.

Also when the first talk key K220 is thus operated there is completed, at the contacts 224 thereof, an obvious circuit for energizing the winding of the answer relay R640, thereby to cause the latter relay to operate. Upon operating, the answer relay R640 completes, at the contacts 645, an obvious circuit for energizing the winding of the hold relay R630, thereby to cause the latter relay to operate. Upon operating, the hold relay R630 completes, at the contacts 631, a multiple circuit for illuminating the first trunk busy lamps L255, etc., at the three operator positions at the control switchboard 200 in order to indicate to the operators thereat that the first control trunk 701 is busy at this time. Also the answer relay R640 interrupts, at the contacts 643, the previously traced circuit for illuminating the first trunk answer lamps L256, etc., at the three operator positions at the control switchboard 200 in order to indicate to the operators thereat that the call on the first control trunk 701 has been answered at one of the operator positions. Finally the answer relay R640 interrupts, at the contacts 642, the previously traced path for connecting ground potential by way of the winding of the impulse relay R620 to the simplex of the winding 697 of the repeater 695; and completes, at the contacts 641, a series circuit for energizing the windings of the impulse relay R540 and the release relay R545 in the toll selector 500 at this time. The last-mentioned circuit extends from ground by way of the winding of R545, the winding of R540, the contacts 443, C981, the wiper 911 of the trunk switch 910 and the engaged contact in the associated contact bank, the contacts 922, C761, the simplex of the winding 711 of the repeater 710, the line conductors in parallel of the first control trunk 701, the simplex of the winding 697 of the repeater 695, the contacts 641,

the contacts 225 of the first trunk talk key K220, the contacts 213 of the release key K212, the contacts 217 of the ring key K215, the dial 206 and the resistor 207 to battery. When this series circuit is completed the impulse relay R540 operates; however, the release relay R545 does not operate as the latter relay is of the marginal type.

Upon operating, the impulse relay R540 completes, at the contacts 542, an obvious circuit, including the contacts 533, for energizing the winding of the hold relay R550, thereby to cause the latter relay to operate. Upon operating, the hold relay R550 completes, at the contacts 554, an obvious circuit for energizing the lower winding of the switch-through relay R530; thereby to render the latter relay exceedingly fast to operate when the intermediate winding thereof is subsequently energized, the switch-through relay R530 being of the polarized type. Also the hold relay R550 completes, at the contacts 555, an obvious multiple holding circuit, including the contacts 462, for energizing the winding of the control relay R460, thereby to retain the latter relay in its operated position at this time; the operated control relay R460 retaining operated the connect relay R920 and the cutoff relay R950 in the first control trunk equipment 901, as previously noted.

At this time the operator at the first operator position 201 learns the destination of the present connection and proceeds to operate the toll selector 500 of the third toll link 503 in order to extend the connection. This is accomplished by operating the dial 206 in order to cause a digit to be transmitted over the previously traced connection, including the first control trunk 701, to the impulse relay R540 in the toll selector 500.

Extension of a call to the distant office

Assuming that the call in the present example is to be extended to the distant office 41, the operator at the first operator position 201 at the control switchboard 280 operates the dial 206 in accordance with a predetermined digit, whereby the digit is transmitted over the first control trunk 701 to the impulse relay R540, as previously noted. The impulse relay R540 follows the impulses of the digit mentioned, restoring and re-operating intermittently a number of times corresponding to the number of impulses in the digit mentioned. Each time the impulse relay R540 restores and then reoperates it interrupts and then recompletes, at the contacts 542, the previously traced circuit for energizing the winding of the hold relay R550; whereby the latter relay, being of the slow-to-release type, is retained operated during impulsive. Also each time the impulse relay R540 restores and then reoperates it completes and then interrupts, at the contacts 541, a circuit, including the contacts 533, 522 and 561, for energizing the vertical magnet M514 in multiple with the lower winding of the transfer relay R560; whereby the vertical magnet M514 operates and restores, thereby to drive the wiper carriage of the switch mechanism 510 one step in the vertical direction; and whereby the transfer relay R560 is retained operated during impulsive as the latter relay is of the slow-to-release type.

When the wiper carriage of the switch mechanism 510 is driven one step in the vertical direction away from its normal vertical position the sets of switch springs S519, S520 and S521 are actuated. More particularly, the set of switch

springs S519 is actuated into engagement, thereby to prepare a circuit traced hereinafter for energizing the winding of the control relay R480 in multiple with the release magnet M517; the set of switch springs S520 is actuated into disengagement, thereby to interrupt the previously traced circuit for energizing the upper winding of the transfer relay R560; and the set of switch springs S521 is actuated into engagement, thereby to prepare a circuit traced hereinafter for energizing the rotary magnet M515. At the conclusion of the digit mentioned the impulse relay R540 is retained in its operated position, thereby to retain operated the hold relay R550 and to effect the restoration of the transfer relay R560 shortly thereafter; the transfer relay R560 being of the slow-to-release type, as previously noted. Upon restoring, the transfer relay R560 completes, at the contacts 562, the previously mentioned circuit for energizing the rotary magnet M515; the last-mentioned circuit extending from ground by way of the contacts 533 and 542, the set of switch springs S521, the contacts 562 and 516 and the rotary magnet M515 to battery. When thus energized the rotary magnet M515 operates to drive the wiper carriage of the switch mechanism 510 one step in the rotary direction away from its normal rotary position and to interrupt, at the contacts 516, the previously traced circuit for energizing the rotary magnet M515. The rotary magnet M515 then restores, thereby to recomplete, at the contacts 516, the previously traced circuit for energizing the rotary magnet M515.

Accordingly the rotary magnet M515 operates and restores intermittently, thereby to drive the wiper carriage of the switch mechanism 510 step by step in the rotary direction until an idle toll line extending to the distant office 41 is tested. More particularly, when the wiper set carried by the wiper carriage engages a contact set in the associated contact bank terminating a busy toll line, ground potential is applied to the control wiper 513 thereof; thereby to complete an obvious path, including the contacts 553 and the grounded hold conductor C485, for short-circuiting the intermediate winding of the switch-through relay R530. On the other hand, when the wiper set carried by the wiper carriage engages a contact set in the associated contact bank terminating an idle toll line, battery potential is applied to the control wiper 513 thereof; thereby to complete an obvious circuit, including the contacts 553 and the grounded hold conductor C485, for energizing the intermediate winding of the switch-through relay R530. When the intermediate winding of the switch-through relay R530 is thus energized it operates exceedingly fast to complete, at the contacts 534, an obvious holding circuit, including the contacts 462 and the grounded hold conductor C485, for energizing the upper winding thereof; and to interrupt, at the contacts 532, a further point in the previously traced circuit for energizing the rotary magnet M515, thereby positively to arrest further operation of the switch mechanism 510 at this time.

Assuming that the toll line 301 is the first idle toll line in the group extending to the distant office 41, when the wiper set carried by the wiper carriage engages the contact in the associated contact bank terminating the toll line mentioned, the switch-through relay R530 operates as explained above. The toll line 301 is marked as idle to the toll selector 500 by the presence of battery potential by way of the winding of the cutoff relay R320 in the toll line circuit 310 and the

contacts 327 to the control conductor C304 thereof. Also, upon operating, the switch-through relay R530 completes, at the contacts 535, an obvious path for applying ground potential to the control wiper 513, thereby to complete a circuit substantially identical to that previously traced for energizing the winding of the cutoff relay R330 in the toll line circuit 310. When thus energized the cutoff relay R330 operates to complete, at the contacts 331, an obvious connection, including the contacts 327, between the grounded control conductor C304 and the control conductor C305; thereby positively to mark the toll line 301 as busy to the toll finders of the various toll links having access thereto. Further the cutoff relay R330 interrupts, at the contacts 332, a point in a circuit traced hereinafter for energizing the lower winding of the ring-up relay R320 in series with the winding of the start relay R325; and interrupts, at the contacts 333, a further point in a path traced hereinafter for applying ground potential in the toll line circuit 310 to the start conductor C155 extending to the common equipment 800. Also, the switch-through relay R530 prepares, at the contacts 536, a circuit traced hereinafter for energizing the winding of the ring relay R570; and completes, at the contacts 531 and 532, a connection between the toll finder 400 and the toll selector 500.

The operator at the first operator position 201 at the control switchboard 200 then proceeds to operate the toll selector 500 to ring down the toll line 301 seized thereby and extending to the toll operator position 42 in the distant office 41. This is accomplished by operating and restoring repeatedly the ring key K215 at the first operator position 201. Each time the ring key K215 is operated there is completed, at the contacts 216 thereof, an obvious alternative circuit, including the generator conductor C210, for energizing in series the winding of the impulse relay R540 and the winding of the release relay R545; whereby the impulse relay R540 is retained in its operated position and the release relay R545 is retained in its restored position, as previously explained. Also the ringing voltage impressed upon the generator conductor C210 completes a circuit substantially identical to that previously traced and including the contacts 536 and the condenser 524 for energizing the winding of the ring relay R570 in order to cause the latter relay to operate. Also each time the ring key K215 is operated there is interrupted, at the contacts 217 thereof, the previously traced original circuit, including the dial 206, for energizing in series the winding of the impulse relay R540 and the winding of the release relay R545. Each time the ring key K215 is restored there is recompleted, at the contacts 217 thereof, the previously traced original circuit for energizing in series the winding of the impulse relay R540 and the winding of the release relay R545; and there is interrupted, at the contacts 216 thereof, the previously traced alternative circuit for energizing the winding of the impulse relay R540 in series with the winding of the release relay R545 and also the multiple circuit for energizing the winding of the ring relay R570, whereupon the latter relay restores. Accordingly the ring key K215 is operated repeatedly in order to cause a corresponding number of operations and restorations of the ring relay R570 in the toll selector 500. Each time the ring relay R570 operates it effects operation of the ring slave relay R580; which latter relay operates to interrupt, at the

contacts 581 and 583, the previously mentioned connection between the toll selector 500 and the toll finder 400, and to complete, at the contacts 584 and 582, obvious paths for applying ground and ring potentials, respectively, to the line wipers 512 and 511 of the wiper set; the path for applying ringing potential to the line wiper 511 including the ring conductor C523. Accordingly ringing current is projected from the toll selector 500 over the toll line 301, thereby to effect operation of the ring-up relay R320 in the toll line circuit 310 without effect at this time and to ring down the position equipment at the toll operator position 42 in the distant office 41 in accordance with conventional practice. Each time the ring relay R570 restores it effects the restoration of the ring slave relay R580; which latter relay interrupts, at the contacts 582 and 584, the previously traced path for projecting ringing current over the toll line 301, and recompiles, at the contacts 581 and 583, the previously mentioned connection between the toll finder 400 and the toll selector 500.

The operator at the toll operator position 42 in the distant office 41 answers the call in accordance with conventional practice, whereby a connection is established from the toll operator position 42 via the toll line 301, the line wipers 511 and 512, the contacts 581 and 583 and the contacts 531 and 532 to the conductors C983 and C982; the calling subscriber substation T in the remote office 31 is connected via the subscriber line 341, the local link 344 and the C. L. R. trunk 390 to the repeater 351 in the C. L. R. trunk circuit 350; the repeater 351 in the C. L. R. trunk circuit 350 is connected via the trunk 395, the line wipers 401 and 402 of the access switch 410 and the contacts 421 and 451 to the conductors C983 and C982; the conductors C983 and C982 are connected via the wipers 913 and 912 of the trunk switch 910, the contacts 926 and 924 and the conductors C763 and C762 to the repeater 710; the repeater 710 is connected via the first control trunk 701 to the repeater 695; and the repeater 695 is connected to the telephone set 205 at the first operator position 201 at the control switchboard 200 in the central office 21. Accordingly, at this time, a three-way communication connection is established between the calling subscriber substation T in the remote office 31, the called toll operator position 42 in the distant office 41 and the answering first operator position 201 at the control switchboard 200 in the central office 21. The operator at the first operator position 201 then advises the operator at the toll operator position 42 concerning the extension of the call, whereupon the last-mentioned operator extends the call in accordance with conventional practice.

After the call has been extended by the operator at the toll operator position 42 and has been completed to the called destination, the operator at the first operator position 201 disconnects the associated operator position from the first control trunk 701 by restoring the first trunk talk key K220. When the first trunk talk key K220 is thus restored there is interrupted, at the contacts 223 and 226 thereof, the previously traced connection between the telephone set 205 and the winding 896 of the repeater 695; there is interrupted, at the contacts 222 thereof, the previously mentioned path for applying ground potential to the conductor C291 extending to the interrupter 26; there is interrupted, at the contacts 221 thereof, a further point in the previously

traced circuit for flashing the third link hold lamp L254; and there is interrupted, at the contacts 224 thereof, the previously traced circuit for energizing the winding of the answer relay R640 in order to cause the latter relay to restore. Finally when the first trunk talk key K220 is restored there is interrupted, at the contacts 225 thereof, the previously traced circuit for energizing the winding of the impulse relay R540 in series with the winding of the release relay R545, whereupon the impulse relay R540 restores. Upon restoring, the answer relay R640 completes, at the contacts 644, the previously mentioned circuit, including the contacts 632 and the set of switch springs S617, for energizing the release magnet M615; whereupon the latter magnet operates in order to release the wipers noted of the lamp switch 610, whereupon the wipers noted are returned to their normal rotary positions. When the lamp switch 610 is thus released the sets of switch springs S616 and S617 are actuated into disengagement. More particularly, the set of switch springs S616 is actuated into disengagement, thereby to interrupt a further point in the previously traced circuit for illuminating the first trunk answer lamps L256 etc. at the three operator positions at the control switchboard 200; and the set of switch springs S617 is actuated into disengagement, thereby to interrupt the previously traced circuit for energizing the release magnet M615. Also, upon restoring, the answer relay R640 interrupts, at the contacts 645, the previously mentioned circuit for energizing the winding of the hold relay R630; thereby to cause the latter relay to restore shortly thereafter, the hold relay R630 being of the slow-to-release type. Upon restoring, the hold relay R630 interrupts, at the contacts 631, the previously mentioned alternative circuit for illuminating the first trunk busy lamps L255 etc. at the three operator positions at the control switchboard 200.

Upon restoring, the impulse relay R540 interrupts, at the contacts 543, an obvious multiple holding circuit, including the contacts 462, for energizing the winding of the control relay R460, thereby to cause the latter relay to restore. Upon restoring, the control relay R460 interrupts, at the contacts 461, the previously traced holding circuit for energizing the winding of the connect relay R920 in multiple with the upper winding of the cutoff relay R950, thereby to cause the latter relays to restore. Upon restoring, the cutoff relay R950 recompletes, at the contacts 953, the previously traced connection between the chain start conductor C862 and the winding of the switch start relay R960, thereby to render the first control trunk equipment 901 available to the use of a calling one of the toll links in the associated group in view of the fact that the first control trunk equipment 901 is completely released at this time and the first control trunk 701 is idle at this time. Upon restoring, the connect relay R920 interrupts, at the contacts 924 and 926, the previously traced connection between the repeater 710 and the wipers 912 and 913 of the trunk switch 910; and recompletes, at the contacts 923 and 925, the previously mentioned connection between the repeater 710 and the wipers 883 and 882 of the monitor switch 880. Also the connect relay R920 interrupts, at the contacts 922, the previously traced connection between the simplex of the winding 711 of the repeater 710 and the wiper 811 of the trunk switch 910; and recompletes, at the contacts 921, the previously traced connection between the simplex of the winding 711 of the re-

peater 710 and the windings of the impulse relay R540 and the release relay R545.

Accordingly, at this time, the connection is set up from the calling subscriber substation in the 5 remote office 31 via the third toll link 503 to the toll operator position 42 in the distant office 41 and is completed from the last-mentioned operator position; this connection being set up entirely independently of the first control trunk 10 701 over which the toll selector 500 of the third toll link 503 was controlled. Also, at this time, the first control trunk equipment 901 and the associated first control trunk 701 are idle and available for further use to a calling one of the toll 15 links in the associated group; and the first operator position 201 at the control switchboard 200 in the central office 21 is idle. However, the operator at the first operator position 201 at the switchboard 200 retains supervision of the connection set up via the third toll link 503 by retaining operated the third link hold key K240, as explained more fully hereinafter.

In the foregoing explanation of the control of the toll selector 500 over the first control trunk 701 from the first operator position 201 at the control switchboard 200, it was assumed that there 25 was an idle toll line in the group extending to the distant office 41 and that the toll selector 500 operated to select the idle toll line 301 in the group mentioned. However, it may occur that, when the toll selector 500 is operated, in the manner previously explained, all of the toll lines in the group extending to the distant office 41 are busy. In this event, the rotary magnet 30 M515 continues to operate intermittently, whereby 35 the wiper carriage of the switch mechanism 510 is driven eleven steps in the rotary direction away from its normal rotary position; whereupon the set of switch springs S522 is actuated into engagement in order to complete an obvious circuit, including the grounded hold conductor C485 and the contacts 482, for energizing the intermediate winding of the switch-through relay R530 in series with the upper winding of the transfer 40 relay R560. When this series circuit is completed the switch-through relay R530 operates, in the manner previously explained, and the transfer relay R560 reoperates. The operator at the first operator position 201 is thus unable to complete 45 the connection to the toll operator position 42 in the distant office 41 in view of the all-busy condition of the trunks in the group extending between the remote office 31 and the distant office 41. In this event, the operator at the first operator position 201 effects the release of the toll 50 selector 500 by momentarily operating the release key K212. When the release key K212 is thus operated there is completed, at the contacts 214 thereof, a circuit substantially identical to that 55 previously traced and including the resistor 209 and the booster battery 208 for energizing the winding of the impulse relay R540 in series with the winding of the release relay R545; and there is interrupted, at the contacts 213 of the release key K212, the previously traced original circuit 60 for energizing the winding of the impulse relay R540 in series with the winding of the release relay R545. When the above-mentioned alternative circuit, including the booster battery 208, is completed for energizing the winding of the impulse relay R540 in series with the winding of the release relay R545, the impulse relay R540 is retained in its operated position and the release relay R545 operates, the release relay R545 being 65 of the marginal type.

Upon operating, the release relay R545 completes, at the contacts 546, an obvious circuit, including the set of switch springs S519, for energizing the release magnet M517 in multiple with the winding of the control relay R480. Shortly after the control relay R480 is thus energized it operates, as it is of the slow-to-operate type, to complete, at the contacts 481, an obvious holding circuit for energizing the winding thereof in multiple with the release magnet M517. Also the control relay R480 interrupts, at the contacts 482, the previously traced circuit for energizing the intermediate winding of the switch-through relay R530 in series with the upper winding of the transfer relay R560 and the previously traced multiple holding circuit for energizing the upper winding of the switch-through relay R530. Accordingly the switch-through relay R530 restores and the transfer relay R560 restores shortly thereafter; the latter relay being of the slow-to-release type, as previously noted. Upon operating, the release magnet M517 releases the wiper carriage of the switch mechanism 510, whereupon it is returned to its normal rotary and vertical positions. When the switch mechanism 510 is thus released the sets of switch springs S519, S520, S521 and S522 are actuated. More particularly, the set of switch springs S519 is actuated into disengagement, thereby to interrupt the previously traced holding circuit for energizing the winding of the control relay R480 in multiple with the release magnet M517, whereupon the control relay R480 restores. Upon restoring, the switch-through relay R530 recompletes, at the contacts 533, the previously traced circuit for energizing the winding of the hold relay R550, thereby to cause the latter relay to operate. Upon restoring, the control relay R480 recompletes, at the contacts 482, the previously traced circuit for energizing the upper winding of the transfer relay R560, thereby to cause the latter relay to reoperate.

The release relay R545 operated only during a brief time interval and then restored when the release key K212 was restored at the first operator position 201 at the control switchboard 200, in the manner previously explained. At this time the impulse relay R540 occupies its operated position, thereby to retain operated the control relay R460 and consequently to retain operated the connect relay R920 and the cutoff relay R950 in the first control trunk equipment 901. At this time the toll selector 500 is completely released and is available for reoperation, in the manner previously explained. Shortly thereafter the operator at the first operator position 201 at the switchboard 200 reoperates the toll selector 500 in order again to make an attempt to extend the connection to the toll operator position 42 in the distant office 41, in the manner explained above.

Supervision and release of an established connection

As previously pointed out, the supervision of the established connection between the calling subscriber substation T in the remote office 31 and the called toll operator position 42 in the distant office 41 is under the control of the operator at the first operator position 201 at the control switchboard 200 in the central office 21, due to the fact that the established connection is completed by way of the third toll link 503 in the remote office 31 and the corresponding third link hold key K240 at the first operator position 75

201 occupies its operated position, as previously noted. The subscriber at the calling subscriber substation T in the remote office 31 initiates the release of the established connection by replacing the receiver of the telephone instrument thereat upon its associated switchhook, thereby to effect the release of the local link 344 in accordance with conventional practice. When the local finder 345 is thus released the line circuit 342 operates in order to mark the subscriber line 341 extending to the subscriber substation T as idle to the local connectors having access thereto. When the local connector 346 is thus released the previously traced circuit for energizing in series the upper and lower windings of the line relay R360 is interrupted, thereby to cause the latter relay to restore. Upon restoring, the line relay R360 completes, at the contacts 362, an obvious path, including the contacts 375 and 383, for applying ground potential to the control conductor C398 of the trunk 395 extending to the C. L. R. trunk circuit 350, thereby to complete an obvious alternative holding circuit for energizing the winding of the cutoff relay R380 and an obvious path, including the wiper 403 of the access switch 410 and the engaged contact in the associated contact bank and the contacts 424 and 428, for short-circuiting the upper winding of the supervisory relay R430 in the toll finder 400. When the upper winding of the supervisory relay R430 is thus short-circuited the latter relay restores in order to recomplete, at the contacts 431, the previously traced original path for short-circuiting the upper winding thereof. Also, upon restoring, the line relay R360 interrupts, at the contacts 361, the previously mentioned circuit for energizing the winding of the start relay R370, thereby to cause the latter relay to restore shortly thereafter, the start relay R370 being of the slow-to-release type. Upon restoring, the start relay R370 interrupts, at the contacts 375, the previously traced path for applying ground potential by way of the contacts 362 and 383 to the control conductor C398 of the trunk 395; however, ground potential in the toll finder 400 is retained upon the control conductor C398 of the trunk 395 in order to retain the cutoff relay R380 in its operated position. The operated cutoff relay R380 retains completed, at the contacts 384, an obvious multiple path for applying ground potential to the control conductor C398 of the C. L. R. trunk 390 in order to retain the latter trunk marked as busy to the local connectors having access thereto.

Upon restoring, the supervisory relay R430 completes, at the contacts 432, an obvious path, including the contacts 429, for applying ground potential to the supervisory start conductor C866 extending to the common equipment 800; and completes, at the contacts 433, an obvious path for applying battery potential by way of the lower winding of the supervisory relay R430 and the contacts 420 to the third supervisory marking conductor C864 extending to the signal sender 1000. The application of ground potential to the supervisory start conductor C866 completes an obvious circuit, including the contacts 813, 823 and 745, for energizing the winding of the supervisory start relay R630 in the event the common equipment 800 is idle at this time, in order to cause the latter relay to operate. On the other hand, in the event the common equipment 800 is busy at this time, the start relay R740 or one of the sender stop relays R810 and

R820 occupies its operated position in order to prevent operation of the supervisory start relay R830 at this time; whereupon the operation of the supervisory start relay R830 is delayed pending the idle condition of the common equipment 880. Assuming that the common equipment 880 is idle at this time and that the supervisory start relay R830 operates, upon operating, the supervisory start relay R830 completes, at the contacts 831, an obvious alternative circuit for energizing the winding of the sender start relay R840, thereby to cause the latter relay to operate. Upon operating, the sender start relay R840 completes, at the contacts 842, the previously traced circuit for energizing the winding of the cycle relay R870 in order to cause the latter relay to operate. Upon operating, the cycle relay R870 effects operation of the impulse relay R850 and the consequent operation of the cycle relay R860; whereby the cycle relays R860 and R870 and the impulse relay R850 operate repeatedly through a plurality of cycles in order to effect sequential operation of the count relays R1020, R1030, etc., in the signal sender 1000, all in the manner previously explained. When the third count relay R1040 in the signal sender 1000 operates it completes, at the contacts 1046, a series circuit for energizing the winding of the sender stop relay R820 and the lower winding of the supervisory relay R430, the last-mentioned circuit extending from ground by way of the winding of R820, the contacts 835 and 1046, the third supervisory marking conductor C884, the contacts 420 and 433, and the lower winding of R430 to battery. When this series circuit is completed the sender stop relay R820 operates and the supervisory relay R830 reoperates. Upon reoperating, the supervisory relay R830 interrupts, at the contacts 831, the previously mentioned path for short-circuiting the upper winding thereof; whereby the previously traced series holding circuit for energizing the upper winding of the supervisory relay R830 and the cutoff relay R380 is again recompleted. Also the supervisory relay R430 interrupts, at the contacts 432, the previously mentioned path for applying ground potential to the supervisory start conductor C868; and interrupts, at the contacts 433, the above-traced series operating circuit for energizing the winding of the sender stop relay R820 and the lower winding of the supervisory relay R430.

Upon operating, the sender stop relay R820 completes, at the contacts 822, an obvious holding circuit, including the contacts 841 and the resistor 844, for energizing the winding thereof. Further the sender stop relay R820 interrupts, at the contacts 823, the previously traced circuit for energizing the winding of the supervisory start relay R830, thereby to cause the latter relay to restore and interrupt, at the contacts 831, the previously mentioned circuit for energizing the winding of the sender start relay R840; whereupon the latter relay restores shortly thereafter, the sender start relay R840 being of the slow-to-release type. Further the sender stop relay R820 interrupts, at the contacts 824, the previously traced circuit for energizing the winding of the cycle relay R870 in order to cause the latter relay to restore and effect the restoration of the impulse relay R850 and the cycle relay R860; whereby the third count relay R1040 restores in order to effect the release of the signal sender 1000, all in the manner previously explained.

Accordingly the impulse relay R850 operated 75

and restored three times under the control of the signal sender 1000, while the supervisory start relay R830 occupied its operated position, in view of the fact that the supervision was received over the established connection including the third toll link 583. The three operations and restorations of the impulse relay R850 cause three battery impulses to be transmitted at the contacts 852 via the resistor 845 and the contacts 834 over the supervisory conductor C105 to the supervisory equipment 658 in the central office 21; whereby the impulse relay R850 operates and restores three times. Each time the impulse relay R850 operates and restores it completes and then interrupts, at the contacts 891, an obvious circuit for energizing the winding of the hold relay R885; thereby to cause the latter relay to operate and remain operated during impulsion, the hold relay R885 being of the slow-to-release type. Upon operating, the hold relay R885 completes, at the contacts 686, an obvious circuit for energizing the winding of the hold slave relay R880, thereby to cause the latter relay to operate. Also each time the impulse relay R850 operates and restores it completes and then interrupts, at the contacts 882, an obvious circuit for energizing the rotary magnet M662 in order to cause the latter magnet to operate and restore; whereby the wiper 661 of the lamp switch 660 is driven one step in the counterclockwise direction. Accordingly, in the present example, the wiper 661 of the lamp switch 660 is driven three steps in the counterclockwise direction, thereby to prepare a series circuit traced hereinafter for energizing the winding of the third link lock relay R875 and for illuminating the third link supervisory lamp L253 at the first operator position 201 at the control switchboard 200.

Following the conclusion of the three impulses transmitted over the supervisory conductor C105 the impulse relay R850 restores and remains restored in order to interrupt, at the contacts 691, the previously mentioned circuit for energizing the winding of the hold relay R885. Shortly thereafter the hold relay R885 restores to complete, at the contacts 687, the previously mentioned circuit, including the contacts 681, the wiper 661 of the lamp switch 660 and the engaged third contact in the associated contact bank and the contacts 241 of the operated third link hold key K240, for energizing the winding of the third link lock relay R875 and for illuminating the third link supervisory lamp L253. When thus energized the third link lock relay R875 operates to complete, at the contacts 676, an obvious holding circuit for energizing the winding thereof and for illuminating the third link supervisory lamp L253. Also, upon restoring, the hold relay R885 interrupts, at the contacts 686, the previously mentioned circuit for energizing the winding of the hold slave relay R880; thereby to cause the latter relay to restore shortly thereafter, the hold slave relay R880 being of the slow-to-release type. Upon restoring, the hold slave relay R880 completes, at the contacts 682, a circuit, including the contacts 688 and the set of switch springs S684, for energizing the release magnet M663; the set of switch springs S684 being operated into engagement when the wiper 661 of the lamp switch 660 is operated away from its normal rotary position. When thus energized the release magnet M663 operates in order to release the wiper 661 of the lamp switch 660 and to cause it to be returned to its normal rotary position. When the lamp switch 660 is thus released the

set of switch springs S664 is actuated into disengagement, thereby to interrupt the previously traced circuit for energizing the release magnet M663.

At this point it is again noted that the operation of the lamp switch 660 described above is effective to cause operation of the third link lock relay R675 and to cause illumination of only the third link supervisory lamp L253 at the first operator position 201 at the control switchboard 200, in view of the fact that only the third link hold key K240 at the first operator position 201 occupies its operated position at this time. The illumination of the third link supervisory lamp L253 at the first operator position 201 at the control switchboard 200 indicates to the operator thereat that supervision has been received over an established connection set up via the third toll link 503 in the remote office 31. The operator at the first operator position 201 then selects any idle one of the control trunks and operates the corresponding trunk talk key. For example, the operator at the first operator position 201 may select the first control trunk 701 in the event it is idle and operate the corresponding first talk key K220 in order to cause the telephone set 205 at the first operator position 201 to be connected to the winding 696 of the repeater 695, in the manner previously explained. Also when the first trunk talk key K220 is thus operated the answer relay R640 and the hold relay R630 are operated, the hold relay R630 completing, at the contacts 631, the previously traced circuit for illuminating the first trunk busy lamps L255, etc., at the three operator positions at the control switchboard 200. The illumination of the first trunk busy lamps L255, etc., at the three operator positions at the control switchboard 200 indicates to the operators thereat that the first control trunk 701 is busy at this time. Also, upon operating, the answer relay R640 completes, at the contacts 641, the previously traced connection between battery and the simplex of the winding 697 of the repeater 695, including the dial 206, the ring key K215 and the release key K212. When battery potential is thus connected to the simplex of the winding 697 of the repeater 695 an obvious circuit, including the line conductors in parallel of the first control trunk 701, the simplex of the winding 711 of the repeater 710, C761 and the contacts 921, is completed for energizing the winding of the impulse relay R940 in series with the winding of the release relay R945. When this series circuit is completed the impulse relay R940 operates; however, the release relay R945 does not operate as the latter relay is of the marginal type. Upon operating, the impulse relay R940 completes, at the contacts 942, an obvious circuit for energizing the winding of the hold relay R930, thereby to cause the latter relay to operate in order positively to prevent operation of the connect relay R920.

The operator at the first operator position 201 then proceeds to operate the dial 206 in accordance with the digit 3 corresponding to the illumination of the third link supervisory lamp L253 indicating that the established connection routed via the third toll link 503 requires supervision. Accordingly the dial 203 transmits three battery impulses over the previously traced connection, causing the impulse relay R940 to restore and then reoperate three times. Each time the impulse relay R940 restores and reoperates it completes and then interrupts, at the contacts 941, an obvious circuit, including the contacts 75

931, for energizing the rotary magnet M884 in order to cause the latter magnet to operate and restore; whereupon the wipers noted of the monitor switch 880 are driven one step in the clockwise direction away from their normal rotary positions. Hence, at this time, the wipers noted of the monitor switch 880 are driven three steps in the clockwise direction away from their normal rotary positions into engagement with the third contacts in the associated contact banks terminating the conductors C891, C892 and C893 extending to the third toll link 503. Also each time the impulse relay R940 restores and reoperates it interrupts and then recomplete, at the contacts 942, the previously mentioned circuit for energizing the winding of the hold relay R930; however, the latter relay remains operated during impulsion as it is of the slow-to-release type.

Accordingly, at this time, a monitoring connection is completed between the first operator position 201 at the control switchboard 200 and the third toll link 503. More particularly, the telephone set 205 at the first operator position 201 is connected by way of the previously traced path to the repeater 695; the repeater 695 is connected by way of the first control trunk 701 to the repeater 710; and the winding 712 of the repeater 710 is connected by way of the conductors C762, C763 and the contacts 923, 925, the wipers 883, 882 of the monitor switch 880 and the engaged contacts in the associated contact banks to the conductors C893, C892 extending between the toll finder 400 and the toll selector 500 of the third toll link 503. At this time the operator at the first operator position 201 challenges the release of the established connection routed by way of the third toll link 503 and, upon determining that the established connection has been released, she momentarily operates the release key K212. When the release key K212 is thus operated there is completed, at the contacts 214, the previously traced alternative path, including the booster battery 208, for applying booster battery potential to the simplex of the winding 697 of the repeater 695; whereby the impulse relay R940 remains in its operated position and the release relay R945 operates. Upon operating, the release relay R945 completes, at the contacts 946, a path, including the wiper 881 of the monitor switch 880 and the engaged third contact in the associated contact bank, C891 and the contacts 423, for short-circuiting the lower and intermediate windings of the switch-through relay R420, whereupon the latter relay restores. When the release key K212 is then restored the previously traced original path for applying battery potential to the simplex of the winding 697 of the repeater 695 is recompleted, whereupon the impulse relay R940 is retained in its operated position and the release relay R945 restores.

Upon restoring, the switch-through relay R420 interrupts, at the contacts 422, the previously mentioned circuit for energizing the winding of the switch relay R450, thereby to cause the latter relay to restore. Also the switch-through relay R420 interrupts, at the contacts 423, the previously mentioned path for applying ground potential to the hold conductor C485 and the previously traced series holding circuit for energizing the upper winding of the supervisory relay R430 and the winding of the cutoff relay R380, whereupon the relays mentioned restore. Upon restoring, the cutoff relay R380 interrupts, at the contacts 384, the previously mentioned path for

applying ground potential to the control conductor C393 of the C. L. R. trunk 390; thereby to mark the last-mentioned trunk as idle to the local connectors having access thereto. When ground potential is removed from the hold conductor C485 the previously traced holding circuit for energizing the upper winding of the switch-through relay R530 is interrupted, thereby to cause the latter relay to restore. Upon restoring, the switch-through relay R530 interrupts, at the contacts 531 and 532, the previously traced connection between the toll finder 400 and the toll selector 500; and completes, at the contacts 533, an alternative circuit, including the contacts 541, 551 and the set of switch springs S519, for energizing the winding of the control relay R480 in multiple with the release magnet M517. When thus energized the control relay R480 operates to complete, at the contacts 481, the previously traced holding circuit, including the set of switch springs S519, for energizing the winding thereof in multiple with the release magnet M517. The release magnet M517 operates in order to release the wiper carriage of the switch mechanism 510, whereby the switch mechanism 510 is released in the manner previously explained. When the switch mechanism 510 is thus released the sets of switch springs S519, S520 and S521 are actuated, whereby the control relay R480 restores, in the manner previously explained. Finally, upon restoring, the switch-through relay R530 interrupts, at the contacts 535, the previously mentioned path for applying ground potential to the control wiper 513 of the wiper set; thereby to interrupt the previously traced circuit for energizing the winding of the cutoff relay R430 in order to cause the latter relay to restore. When ground potential is removed from the control conductor C394 of the toll line 381 the toll line circuit 380 is then completely released and the toll line 381 extending between the remote office 31 and the distant office 41 is marked as idle to the toll selectors having access thereto. At this time the third toll link 503 is completely released.

The operator at the first operator position 281 at the control switchboard 200 then restores the first trunk talk key K220, thereby to disconnect the telephone set 285 from the winding 696 of the repeater 695 and to effect the restoration of the answer relay R640 and the impulse relay R840, in an obvious manner. At this time the operator also restores the key K240, thereby to deenergize the relay R875 and the lamp L253. Upon restoring, the answer relay R640 effects the restoration of the hold relay R830, whereby the latter relay interrupts, at the contacts 831, the previously mentioned circuit for illuminating the first trunk busy lamps L255, etc., at the three operator positions at the control switchboard 200 in order to indicate to the operators thereat that the first control trunk 701 is now idle, all in the manner previously explained. Upon restoring, the impulse relay R840 interrupts, at the contacts 842, the previously mentioned circuit for energizing the winding of the hold relay R930; thereby to cause the latter relay to restore shortly thereafter, the hold relay R930 being of the slow-to-release type, as previously noted. Upon restoring, the hold relay R930 completes, at the contacts 935, an obvious circuit, including the set of switch springs S886, for energizing the release magnet M885; the set of switch springs S886 being actuated into engagement when the wipers noted of the monitor

switch 880 were driven away from their normal rotary positions. When thus energized the release magnet M885 operates to release the wipers noted of the monitor switch 880 and to cause them to be returned to their normal rotary positions, whereupon the set of switch springs S886 is actuated into disengagement. Also, upon restoring, the hold relay R930 recompletes, at the contacts 934, the previously traced circuit for connecting the winding of the switch start relay R960 to the chain start conductor C862; thereby to mark the first control trunk equipment 901 as idle to the various toll links in the associated group, the first control trunk equipment 901 being completely released at this time.

In view of the foregoing explanation of the mode of operation of the third toll link 503 in conjunction with the C. L. R. trunk circuit 350 and the common equipment 800, incident to the release of the established connection between the calling subscriber substation T in the remote office 31 and the toll operator position 42 in the distant office 41 and routed via the third toll link 503, it will be understood that it is not necessary for the subscriber at the calling subscriber substation T completely to release the local link 344 in order to cause the supervisory signal to be transmitted over the supervisory conductor C705 to the operator at the first operator position 281 at the control switchboard 200, in the manner described above. In other words, the subscriber at the calling subscriber substation T has switchhook supervision and may effect momentary restoration of the line relay R368 by momentarily replacing and then removing the receiver of the telephone instrument thereat from its associated switchhook. In this event, the line relay R368 restores and immediately reoperates, thereby to complete and then to interrupt, at the contacts 362, the previously traced path for applying ground potential to the control conductor C398 of the trunk 395 extending to the C. L. R. trunk circuit 350 without effecting the restoration of the start relay R370 and the release of the local link 344. In this event, the subscriber at the calling subscriber substation T retains the local link 344 in its operated position and the connection to the C. L. R. trunk circuit 350; and the momentary application of ground potential to the control conductor C398 of the trunk 395 effects the restoration of the supervisory relay R480 in the toll finder 400, in the manner previously explained. Upon restoring, the supervisory relay R480 initiates operation of the common equipment 800 and the consequent operation of the signal sender 1800, whereby the third link supervisory lamp L253 at the first operator position 281 at the control switchboard 200 is operated in the manner previously explained. In this event, the operator at the first operator position 281 then selects an idle control trunk, such, for example, as the first control trunk 701, and operates the associated first trunk talk key K220 and then operates the dial 286 in accordance with the digit 3; whereby the monitor switch 880 in the first control trunk equipment 901 seizes the third toll link 503, all in the manner previously explained. In this event, a three-way communication connection is completed, including the established connection between the calling subscriber substation T in the remote office 31 and the called toll operator position 42 in the distant office 41; the last-mentioned connection comprising the branch including the first control trunk 701. More particularly, the first operator

position 201 is connected by way of the first control trunk 101 and the monitor switch 880 of the first control trunk equipment 901 to the conductors C983 and C982 extending between the toll finder 400 and the toll selector 500, all in the manner previously explained.

In the present example, after the operator at the first operator position 201 converses with the subscriber at the calling subscriber substation T in the remote office 31 and the operator at the called toll operator position 42 in the distant office 41, she may release the connection between the first operator position 201 and the established connection mentioned without releasing the third toll link 503 or she may retain a monitoring connection to the third toll link 503 as long as she desires. When the operator at the first operator position 201 at the control switchboard 200 desires to release the monitoring connection to the third toll link 503 without releasing the established connection involving the third toll link 503, she merely restores the first talk key K220, whereby the impulse relay R940 restores, in the manner previously explained. Upon restoring, the impulse relay R940 effects the restoration of the hold relay R930; whereby the monitor switch 880 is released, rendering the first control trunk equipment 901 idle, all in the manner previously explained.

At this time the established connection between the calling subscriber substation T in the remote office 31 and the called toll operator position 42 in the distant office 41 is maintained and the supervisory relay R430 in the toll finder 400 occupies its operated position. Hence the subscriber at the calling subscriber substation T may again require supervision and may again initiate either switchhook or release supervision, in the manner described above. After the established connection is completely released the operator at the toll operator position 42 will disconnect the cord circuit therat from the toll line 301 in accordance with conventional practice.

Initiation of a toll call at the toll operator position in the distant office

Considering now the initiation of a toll call at the toll operator position 42 in the distant office 41, the operator at the toll operator position 42 first selects an idle toll line, such, for example, as the toll line 301 and connects thereto. After the operator at the toll operator position 42 connects to the toll line 301 she operates the associated position equipment in order to cause ringing current to be projected thereto in order to complete an obvious circuit, including the contacts 321 and the condenser 324, for energizing the upper winding of the ring-up relay R320. When thus energized the ring-up relay R320 operates to complete, at the contacts 322, an obvious circuit, including the contacts 332, for energizing the lower winding thereof in series with the winding of the start relay R325; whereby the ring-up relay R320 remains in its operated position and the start relay R325 operates. Upon operating, the start relay R325 completes, at the contacts 329, an obvious path, including the contacts 333, for applying ground potential to the start conductor C755 extending to the common equipment 800; and completes, at the contacts 328, an obvious path for applying ground potential to the control conductor C304 of the toll line 301, thereby to mark the toll line 301 as busy to the toll selectors having access thereto. Further the start relay R325 com-

pletes, at the contacts 326, an obvious path for applying battery potential by way of the winding of the cutoff relay R330 to the control conductor C305 of the toll line 301, thereby to mark the toll line 301 as a calling toll line to the toll finders of the toll links having access thereto.

The application of ground potential to the start conductor C755 causes operation of the start relay R740 in the event the common equipment 800 is idle and one of the three control trunk equipments is idle, in the manner previously explained. Upon operating, the start relay R740 effects operation of the finder switch 720 in order to select an idle toll link in the associated group, such, for example, as the third toll link 503, all in the manner previously explained. When the third toll link 503 is selected by the finder switch 720 the cutoff relay R750 operates in order to effect operation of the equipment start relay R440. Upon operating, the equipment start relay R440 effects operation of the supervisory relay R430, applies ground potential to the hold conductor C485, effects operation of the transfer relay R560 and causes operation of the access switch 410, all in the manner previously explained. The access switch 410 is operated to seize the toll line 301, whereupon an obvious circuit for energizing the upper winding of the switch-through relay R420 in series with the winding of the cutoff relay R330 is completed in order to cause the switch-through relay R420 to operate exceedingly fast. Upon operating, the switch-through relay R420 completes, at the contacts 424, the previously traced path for short-circuiting the upper winding thereof; and completes, at the contacts 423 and 424, the previously traced holding circuit for energizing the intermediate winding thereof. Also the switch-through relay R420 completes, at the contacts 423, an obvious holding circuit for energizing the upper winding of the supervisory relay R430 in series with the winding of the cutoff relay R330, thereby to retain the supervisory relay R430 in its operated position and to effect operation of the cutoff relay R330. Upon operating, the cutoff relay R330 interrupts, at the contacts 332, the previously traced holding circuit for energizing the lower winding of the ring-up relay R320 in series with the winding of the start relay R325, thereby to cause the ring-up relay R320 and the start relay R325 to restore. Also the cutoff relay R330 completes, at the contacts 331, an obvious multiple point in the previously traced holding circuit for energizing the winding thereof in series with the upper winding of the supervisory relay R430. At this time the toll finder 400 has operated to seize the toll line 301 extending to the calling toll operator position 42 in the distant office 41.

Also, upon operating, the switch-through relay R420 effects the operation of the switch relay R450 and the latter relay completes, at the contacts 453, the previously traced path for applying ground potential to the chain start conductor C862; whereby an idle one of the three control trunk equipments is taken for use, such, for example, as the first control trunk equipment 901, all in the manner previously explained. When the first control trunk equipment 901 is taken for use the trunk switch 910 is operated to seize the calling third toll link 503; the connect relay R920 is operated to connect the trunk switch 910 to the first control trunk 701; and the signal sender 1000 is operated to send three battery impulses over the code conductor C863 and the

first control trunk 701 to the first control trunk terminal equipment 601, all in the manner previously explained. The impulse relay R620 in the first control trunk terminal equipment 601 responds to the three battery impulses transmitted over the control trunk 701 in order to effect operation of the hold relay R625 and operation of the lamp switch 610, all in the manner previously explained. Subsequently, the hold relay R625 restores to complete, at the contacts 627, the previously traced circuit for illuminating the first trunk answer lamps L256 etc. at the three operator positions at the control switchboard 200 in order to indicate the presence of a call waiting to be answered on the first control trunk 701, in the manner previously explained.

The operator at the first operator position 201 may answer the call on the first control trunk 701 by operating the corresponding first trunk talk key K220 in order to complete a connection therefrom by way of the first control trunk 701, the first control trunk equipment 901 and the trunk switch 910 to the third toll link 503, in the manner previously explained. The operator at the calling toll operator position 42 in the distant office 41 then advises the operator at the first operator position 201 at the control switchboard 200 in the central office 21 concerning the extension of the call.

The operator at the first operator position 201 at the control switchboard 200 then extends the call by suitably operating the dial 206, whereby the toll selector 500 of the third toll link 503 is selectively operated over the first control trunk 701, in the manner previously explained. For example, the toll selector 500 may be operated to seize the utility trunk 591, whereby the call may be extended over equipment, not shown, to the called subscriber substation T in the remote office 31. After the call has thus been extended the operator at the first operator position 201 restores the first trunk talk key K220, the third link hold key K240 having previously been operated. When the first trunk talk key K220 is restored the first control trunk 701 and the first control trunk equipment 901 are released, in the manner previously explained, and the established connection is routed via the third toll link 503 independently of the first operator position 201 at the control switchboard 200. The operator at the first operator position 201 at the control switchboard 200 in the central office 21 retains supervision of the above-mentioned established connection. The release of the above-mentioned established connection is initiated by the operator at the toll operator position 42 in the distant office 41 by operating the associated position equipment; thereby to cause ringing current to be projected over the toll line 301, whereby the ring-up relay R320 is momentarily operated in the manner previously explained. Upon operating, the ring-up relay R320 completes, at the contacts 323, an obvious path, including the contacts 334, for applying ground potential to the control conductor C305 of the toll line 301; thereby to complete an obvious multiple holding circuit for energizing the winding of the cutoff relay R330 and an obvious path, including the wiper 403 of the access switch 410 and the engaged contact in the associated contact bank and the contacts 424 and 423, for short-circuiting the upper winding of the supervisory relay R430.

The supervisory relay R430 then restores, thereby to effect operation of the common equip-

ment 800; whereby the signal sender 1000 is operated to transmit the supervisory signal indicative of the third toll link 503 over the supervisory conductor C705 to the supervisory equipment 650 in order to cause illumination of the third link supervisory lamp L253 at the first operator position 201 at the control switchboard 200, all in the manner previously explained. The operator at the first operator position 201 at the control switchboard 200 then selects an idle one of the control trunks and operates the corresponding trunk talk key. Assuming that the idle first control trunk 701 is selected, the first trunk talk key K220 is operated. The dial 206 is then operated in accordance with the digit 3, thereby to cause the monitor switch 880 in the first control trunk equipment 901 to seize the third toll link 503. The operator at the first operator position 201 then challenges the established connection to determine whether the operator at the toll operator position 42 in the distant office 41 requires supervision or has initiated the release of the established connection by ringing off, in the manner previously explained. The operator at the first operator position 201 then renders the supervisory service or effects the release of the third toll link 503 and the subsequent release of the first control trunk 701, all in the manner previously explained.

Conclusions

From the foregoing it is apparent that a telephone system is provided which comprises a central office, including a control switchboard having a plurality of operator positions, and a remote office or switching center, including a plurality of switching links; whereby calls may be set up by way of the switching links in the remote office over an idle one of a number of two-wire control trunks extending between the central office and the remote office and supervised over a single control conductor extending between the central office and the remote office, under the control of the operator at any one of the operator positions at the control switchboard.

While one embodiment of the invention has been disclosed, it will be understood that various modifications may be made therein which are within the true spirit and scope of the invention.

What is claimed is:

1. In a telephone system, a plurality of lines, a group of links, a plurality of control trunks, an operator position, automatic means for connecting an idle one of said links to a calling one of said lines and for connecting said one link to an idle one of said control trunks and for transmitting a signal over said one control trunk indicative of said one link, means controlled by the signal transmitted over said one control trunk for indicating to said operator position the particular link in said group which is connected thereto, and means controllable over said one control trunk from said operator position for connecting said one link to a called one of said lines.

2. In a telephone system, a plurality of lines, a group of links, a plurality of control trunks each including a pair of talking conductors, an operator position, automatic means for connecting an idle one of said links to a calling one of said lines and for connecting said one link to an idle one of said control trunks and for trans-

mitting a signal over a circuit including at least one of the taking conductors of said one control trunk indicative of said one link, means controlled by the signal transmitted over said circuit for indicating to said operator position the particular link in said group which is connected to said one control trunk, and means controllable over said one control trunk from said operator position for connecting said one link to a called one of said lines.

3. In a telephone system, a plurality of lines, a group of links, a plurality of control trunks each of the two-conductor type, an operator position, automatic means for connecting an idle one of said links to a calling one of said lines and for connecting said one link to an idle one of said control trunks and for transmitting a signal over said one control trunk indicative of said one link, means controlled by the signal transmitted over said one control trunk for indicating to said operator position the particular link in said group which is connected thereto, and means controllable over said one control trunk from said operator position for connecting said one link to a called one of said lines.

4. In a telephone system, a plurality of lines, a group of links, a plurality of control trunks, an operator position, automatic means for connecting an idle one of said links to a calling one of said lines and for connecting said one link to an idle one of said control trunks and for transmitting a series of impulses over said one control trunk indicative of said one link, impulse counting means controlled by the series of impulses transmitted over said one control trunk for indicating to said operator position the particular link in said group which is connected thereto, and means controllable over said one control trunk from said operator position for connecting said one link to a called one of said lines.

5. In a telephone system, a plurality of lines, a group of links, a plurality of control trunks, an operator position, automatic means for connecting an idle one of said links to a calling one of said lines and for connecting said one link to an idle one of said control trunks, a signal sender, means controlled by the connection of said one link to said one control trunk for initiating operation of said signal sender to send impulses over said one control trunk and to test the links in said group, means controlled by the testing of said one link as being connected to said one control trunk for arresting operation of said signal sender, whereby said signal sender is selectively operated to send over said one control trunk a series of impulses indicative of said one link, means controlled by the series of impulses sent over said one control trunk for indicating to said operator position the particular link in said group which is connected thereto, and means controllable over said one control trunk from said operator position for connecting said one link to a called one of said lines.

6. In a telephone system, a plurality of lines, a group of links, a plurality of control trunks, an operator position, first allotter means responsive to the presence of a calling one of said lines for allotting an idle one of said links and for connecting said allotted link to said calling line, .70 second allotter means responsive to the connection of an allotted one of said links to a calling line for connecting said allotted link to an idle one of said control trunks, means responsive to the connection of any one of said links to any

one of said control trunks for transmitting a signal over said one control trunk indicative of said one link, means controlled by the signal transmitted over said one control trunk for indicating to said operator position the particular link in said group which is connected thereto, and means controllable over said one control trunk from said operator position for connecting said one link to a called one of said lines.

7. In a telephone system, a plurality of lines, a group of links, a control trunk, an operator position, automatic means for connecting an idle one of said links to a calling one of said lines and for connecting said one link to said control trunk and for transmitting a signal over said control trunk indicative of said one link, apparatus associated with said control trunk for registering a signal received thereover and for indicating a call thereon, means at said operator position for answering a call on said control trunk, means controlled by the answering of a call on said control trunk at said operator position for causing said apparatus to transmit the registered signal received over said control trunk to said operator position, and means controllable over said control trunk from said operator position for connecting said one link to a called one of said lines.

8. In a telephone system, a plurality of lines, a group of links, a control trunk, a plurality of operator positions, automatic means for connecting an idle one of said links to a calling one of said lines and for connecting said one link to said control trunk and for transmitting a signal over said control trunk indicative of said one link, apparatus associated with said control trunk for registering a signal received thereover and for indicating a call thereon, means at each of said operator positions for answering a call on said control trunk, means controlled by the answering of a call on said control trunk at any one of said operator positions for causing said apparatus to transmit the registered signal received over said control trunk to said one operator position, and means controllable over said control trunk from said one operator position for connecting said one link to a called one of said lines.

9. In a telephone system, a plurality of lines, a group of links, a plurality of control trunks, an operator position, automatic means for connecting an idle one of said links to a calling one of said lines and for connecting said one link to an idle one of said control trunks and for transmitting a signal over said one control trunk indicative of said one link, apparatus associated with said control trunks for registering a signal received over any one of said control trunks and for indicating a call on the corresponding one of said control trunks, means at said operator position for answering a call on any one of said control trunks, means controlled by the answering of a call on any one of said control trunks at said operator position for causing said apparatus to transmit the registered signal received over said one control trunk to said operator position, and means controllable over said one control trunk from said operator position for connecting said one link to a called one of said lines.

10. In a telephone system, a plurality of lines, a group of links, a plurality of control trunks, a plurality of operator positions, automatic means for connecting an idle one of said links to a calling one of said lines and for connecting said one link to an idle one of said control trunks and for transmitting a signal over said one control trunk

indicative of said one link, apparatus associated with said control trunks for registering a signal received over any one of said control trunks and for indicating a call on the corresponding one of said control trunks, means at each of said operator positions for answering a call on any one of said control trunks, means controlled by the answering of a call on any one of said control trunks at any one of said operator positions for causing said apparatus to transmit the registered signal received over said one control trunk to said one operator position, and means controllable over said one control trunk from said one operator position for connecting said one link to a called one of said lines.

11. In a telephone system, a plurality of lines, a group of links, a control trunk, an operator position, automatic means for connecting an idle one of said links to a calling one of said lines and for connecting said one link to said control trunk and for transmitting a signal over said control trunk indicative of said one link, apparatus associated with said control trunk for registering a signal received thereover and for indicating a call thereon, a group of signals associated with said operator position and individually corresponding to said links, means at said operator position for answering a call on said control trunk, means controlled by the answering of a call on said control trunk at said operator position for causing said apparatus to operate the signal in said group corresponding to the registered signal received over said control trunk, and means controllable over said control trunk from said operator position for connecting said one link to a called one of said lines.

12. In a telephone system, a plurality of lines, a group of links, a plurality of control trunks, a plurality of operator positions, automatic means for connecting an idle one of said links to a calling one of said lines and for connecting said one link to an idle one of said control trunks and for transmitting a signal over said one control trunk indicative of said one link, apparatus associated with said control trunks for registering a signal received over any one of said control trunks and for indicating a call on the corresponding one of said control trunks, a plurality of groups of signals individually associated with said operator positions, the signals in each of said groups individually corresponding to said links, means at each of said operator positions for answering a call on any one of said control trunks, means controlled by the answering of a call on any one of said control trunks at any one of said operator positions for causing said apparatus to operate in the group of signals associated with said one operator position the signal corresponding to the registered signal received over said one control trunk.

13. In a telephone system, a first office terminating a plurality of lines and including a group of links, a second office including a plurality of operator positions, a plurality of control trunks extending between said offices, automatic means for connecting an idle one of said links to a calling one of said lines and for connecting said one link to an idle one of said control trunks and for transmitting a signal over said one control trunk indicative of said one link, means responsive to the transmission of a signal over said one control trunk for indicating to said operator positions the presence of a call on said one control trunk, means at each of said operator positions for answering a call on any one of said control trunks,

means controlled jointly by the signal transmitted over said one control trunk and by the answering of the call thereon at any one of said operator positions for indicating to said one operator position the particular link in said group which is connected to said one control trunk, and means controllable over said one control trunk from said one operator position for connecting said one link to a called one of said lines.

14. In a telephone system, a first office terminating a plurality of lines and including a group of links, each of said links including an answer switch and a numerical call switch, a second office including an operator position, a control trunk extending between said offices, automatic means for operating the answer switch of an idle one of said links to seize a calling one of said lines and for connecting said one link to said control trunk and for transmitting a signal over said control trunk indicative of said one link, means controlled by the signal transmitted over said one control trunk for indicating to said operator position the particular link in said group which is connected thereto, and means controllable from said operator position for transmitting one or more digits over said control trunk, thereby to operate the call switch of said one link to seize a called one of said lines.

15. In a telephone system, a first office terminating a plurality of lines and including a group of links, each of said links including an answer switch and a numerical call switch, a second office including an operator position, a control trunk extending between said offices, automatic means for operating the answer switch of an idle one of said links to seize a calling one of said lines and for connecting said one link to said control trunk and for transmitting a signal over said control trunk indicative of said one link, means controlled by the signal transmitted over said one control trunk for indicating to said operator position the particular link in said group which is connected thereto, means controllable from said operator position for transmitting one or more digits over said control trunk, thereby to operate the call switch of said one link to seize a called one of said lines.

16. In a telephone system, a first office terminating a plurality of lines and including a group of links, each of said links including an answer switch and a numerical call switch, a second office including an operator position, a control trunk extending between said offices, automatic means for operating the answer switch of an idle one of said links to seize a calling one of said lines and for connecting said one link to said control trunk and for transmitting a signal over said control trunk indicative of said one link, means controlled by the signal transmitted over said one control trunk for indicating to said operator position the particular link in said group which is connected thereto, means controllable from said operator position for transmitting one or more digits over said control trunk, thereby to operate the call switch of said one link to seize a called one of said lines, and additional means controllable from said operator position for impressing a ring signal upon said control trunk, thereby to cause the call switch of said one link to project ringing current over the seized called line.

17. In a telephone system, a plurality of lines,

a group of links, a control trunk, a supervisory conductor, an operator position, means for setting up a connection from a calling one of said lines by way of any idle one of said links to a called one of said lines, means responsive to the performance of a supervisory control over said connection for transmitting a signal over said supervisory conductor indicative of said one link, means controlled by the signal transmitted over said supervisory conductor for indicating to said operator position the particular link in said group requiring supervision, means for connecting said operator position to said control trunk, and means controllable over said control trunk from said operator position for connecting said control trunk to said one link.

18. In a telephone system, a plurality of lines, a group of links, a control trunk, a switch associated with said control trunk and having access to the links in said group, a supervisory conductor, an operator position, means for setting up a connection from a calling one of said lines by way of any idle one of said links to a called one of said lines, means responsive to the performance of a supervisory control over said connection for transmitting a signal over said supervisory conductor indicative of said one link, means controlled by the signal transmitted over said supervisory conductor for indicating to said operator position the particular link in said group requiring supervision, means for connecting said operator position to said control trunk, and means selectively controllable over said control trunk from said operator position for operating said switch to seize said one link.

19. In a telephone system, a plurality of lines, a group of links, a control trunk, a supervisory conductor, a switch associated with said supervisory conductor, an operator position, a group of signals associated with said operator position and individually corresponding to said links, means for setting up a connection from a calling one of said lines by way of any idle one of said links to a called one of said lines, means responsive to the performance of a supervisory control over said connection for transmitting a signal over said supervisory conductor indicative of said one link, means controlled by the signal transmitted over said supervisory conductor for selectively operating said switch to operate the signal in said group corresponding to said one link, means for connecting said operator position to said control trunk, and means controllable over said control trunk from said operator position for connecting said control trunk to said one link.

20. In a telephone system, a plurality of lines, a group of links, a plurality of control trunks, a supervisory conductor, an operator position, means for setting up a connection from a calling one of said lines by way of an idle one of said links to a called one of said lines, means responsive to the performance of a supervisory control over said connection for transmitting a signal over said supervisory conductor indicative of said one link, means controlled by the signal transmitted over said supervisory conductor for indicating to said operator position the particular link in said group requiring supervision, means for connecting said operator position to any one of said control trunks, and means controllable over said one control trunk from said operator position for connecting said one control trunk to said one link.

21. In a telephone system, a plurality of lines, a group of links, a control trunk, a supervisory

conductor, a plurality of operator positions, means controllable over said control trunk from any one of said operator positions for setting up a connection from a calling one of said lines by way of any one of said links to a called one of said lines, means responsive to the performance of a supervisory control over said connection for transmitting a signal over said supervisory conductor indicative of said one link, means controlled by the signal transmitted over said supervisory conductor for indicating to said one operator position the particular link in said group requiring supervision, means for connecting said one operator position to said control trunk, and means controllable over said control trunk from said one operator position for connecting said control trunk to said one link.

22. In a telephone system, a plurality of lines, a group of links, a plurality of control trunks, a supervisory conductor, a plurality of operator positions, means controllable over any one of said control trunks from any one of said operator positions for setting up a connection from a calling one of said lines by way of any one of said links to a called one of said lines, means responsive to the performance of a supervisory control over said connection for transmitting a signal over said supervisory conductor indicative of said one link, means controlled by the signal transmitted over said supervisory conductor for indicating to said one operator position the particular link in said group requiring supervision, means for connecting said one operator position to any one of said control trunks, and means controllable over said one operator position for connecting said one control trunk to said one link.

23. In a telephone system, a plurality of lines, a group of links, a control trunk, a supervisory conductor, an operator position, means for setting up a connection from a calling one of said lines by way of any idle one of said links to a called one of said lines, a signal sender, means controlled by the performance of a supervisory control over said connection for initiating operation of said signal sender to send impulses over said supervisory conductor and to test the links in said group, means controlled by the testing of said one link as requiring supervision for arresting operation of said signal sender, whereby said signal sender is selectively operated to send over said supervisory conductor a series of impulses indicative of said one link, means controlled by the series of impulses transmitted over said supervisory conductor for indicating to said operator position the particular link in said group requiring supervision, means for connecting said operator position to said control trunk, and means controllable over said control trunk from said operator position for connecting said control trunk to said one link.

24. In a telephone system, a plurality of lines, a group of links, a control trunk, first and second switches associated with said control trunk and having access to said links, an operator position, automatic means for connecting an idle one of said links to a calling one of said lines and for operating said first switch to seize said one link and for connecting said control trunk to said first switch, means controllable over said control trunk and said first switch from said operator position for connecting said one link to a called one of said lines, means controllable over said control trunk from said opera-

tor position for disconnecting said control trunk from said first switch and for connecting said control trunk to said second switch, and means controllable over said control trunk from said operator position for selectively operating said second switch to seize said first link.

25. In a telephone system, a plurality of lines, a group of links, a control trunk, first and second switches associated with said control trunk and having access to said links, an operator position, automatic means for connecting an idle one of said links to a calling one of said lines and for operating said first switch to seize said one link and for connecting said control trunk to said first switch, means controllable from said operator position for selectively connecting said operator position to said control trunk, means controllable over said control trunk from said operator position when it is connected to said first switch for connecting said one link to a called one of said lines, means responsive to the subsequent disconnection of said operator position from said control trunk for disconnecting said control trunk from said first switch and for connecting it to said second switch, and means controllable over said control trunk from said operator position when it is connected to said second switch for operating said second switch to seize said one link.

26. In a telephone system, a plurality of lines, a group of links, a plurality of control trunks, an operator position, means for associating different ones of said links with different ones of said control trunks, means controlled when any one of said links is associated with any one of said control trunks for transmitting over said one control trunk a signal indicative of said one link, means controlled by the signal transmitted over any one of said control trunks for indicating at said operator position the particular link which is associated with said one control trunk, means controllable over any one of said control trunks from said operator position for setting up a connection from a calling one of said lines to a called one of said lines by way of the associated one of said links, a supervisory conductor,

means responsive to the transmission of a supervisory signal over any one of the connections for transmitting a signal over said supervisory conductor indicative of the particular link by way of which said one connection is set up, means controlled by the signal transmitted over said supervisory conductor for indicating at said operator position the particular link requiring supervision, and means controllable over any idle one of said control trunks from said operator position for associating said one control trunk with any one of said links requiring supervision.

27. In a telephone system, a plurality of lines, a group of links, a control trunk, a supervisory conductor, an operator position, automatic means for connecting an idle one of said links to a calling one of said lines and for connecting said one link to said control trunk and for transmitting a signal over said control trunk indicative of said one link, means controlled by the signal transmitted over said control trunk for indicating at said operator position the particular link occupied with the call, means controllable from said operator position for selectively connecting said operator position to said control trunk, means controllable over said control trunk when said operator position is initially connected thereto for connecting said one link to a called one of said lines, thereby to set up a connection between said calling line and said called line by way of said one link, means responsive to the subsequent disconnection of said operator position from said control trunk for disconnecting said one link from said control trunk, means responsive to the transmission of a supervisory signal over said connection for transmitting a signal over said supervisory conductor indicative of said one link, means controlled by the signal transmitted over said supervisory conductor for indicating at said operator position the particular link requiring supervision, and means controllable over said control trunk when said operator position is reconnected thereto for reconnecting said control trunk to said one link.
